Apr. 17, 1923,

1,451,912

A. E. KEITH

TELEPHONE TRUNKING SYSTEM

Original Filed May 21, 1907 9 Sheets-Sheet 2

Witnesses:

P. D. Burfield

A. Andersen.

Inventor:
Alexander E. Keith,
By ~~Bulley & Ward & Murray~~
Attorneys.

Apr. 17, 1923.

1,451,912

A. E. KEITH

TELEPHONE TRUNKING SYSTEM

Original Filed May 21, 1907

9 Sheets-Sheet 3

Witnessed.
R. H. Bumfield
A. Andersen.

Inventor:
Alexander H. Keith,
By Bullock & Tracy,
Attorneys.

Apr. 17, 1923.

1,451,912

A. E. KEITH

TELEPHONE TRUNKING SYSTEM

Original Filed May 21, 1907

9 Sheets-Sheet 4

Heg. 2.

Witnesses.

R. D. Bunsen
A. Andersen.

Inventor:
Alexander E. Keith,
By Bullock and Army,
Attorneys.

Apr. 17, 1923.

UNITED STATES PATENT OFFICE.

ALEXANDER E. KEITH, OF HINSDALE, ILLINOIS, ASSIGNOR, BY MESNE ASSIGNMENTS,
TO AUTOMATIC ELECTRIC COMPANY, OF CHICAGO, ILLINOIS, A CORPORATION OF
ILLINOIS.

TELEPHONE TRUNKING SYSTEM.

Application filed May 21, 1907, Serial No. 374,864. Renewed May 20, 1918. Serial No. 235,694.

To all whom it may concern:

Be it known that I, ALEXANDER E. KEITH, a citizen of the United States of America, and resident of Hinsdale, Du Page County, 5 Illinois, have invented a certain new and useful Improvement in Telephone Trunking Systems, of which the following is a specification.

My invention relates to telephone systems 10 of that character in which automatic trunking is employed between calling and called subscribers. It relates more particularly to systems in which the subscribers' lines are arranged in groups, and in which the exchange apparatus is divided and sub-divided 15 in accordance with the size or capacity of the exchange. Prior to my invention it has been customary, for example, to arrange the subscribers' lines in groups of one hundred each, and to provide ten first-selectors for 20 each group of subscribers' lines. With such arrangement the subscribers are provided with individual trunking switches for enabling them to extend their lines to idle 25 first-selectors. In this way the ten first-selectors allotted to any particular group of subscribers' lines are employed by the subscribers in that group, and are not employed by the subscribers in any other group. Consequently, if all of the first-selectors for any 30 particular group of subscribers are all busy, another subscriber calling from the same group cannot obtain an idle first-selector. Furthermore, with this method of trunking, 35 the percentage of trunking cannot be increased without increasing the number of first-selectors. For example, in an exchange in which the subscribers are arranged in groups of one hundred each, with ten first-selectors for each group, the percentage of 40 trunking could be increased by reducing the number of subscribers in each group to fifty, making twice as many groups as before, and by then doubling the number of first-selectors. With this arrangement the subscribers 45 would be divided into groups of fifty, and the number of first-selectors would be twenty per cent of the total number of subscribers, there being ten first-selectors for each group 50 of fifty subscribers. Evidently, therefore, an increase in the percentage of trunking with a system of this kind would be more or less costly, owing to the increase in the number of selectors, as well as the number

of connectors or final numerical switches by 55 which the connections are completed directly to the called subscribers' lines.

With my improved arrangement, however, the numerical switches, such as first and second selectors and connectors, are so arranged 60 that they are all common to all of the subscribers in the different groups into which the substations of the system are divided. In this way there are no numerical switches 65 which are employed exclusively by certain subscribers, as any calling subscriber has access to any and all first-selectors, as well as to any and all second-selectors and connectors. As herein disclosed, I employ non-numerical trunking switches between the 70 subscribers' individual switches and the first-selectors, and in this way each first-selector is common to all the subscribers of the exchange, or at least to all of the subscribers 75 of a plurality of the groups into which the system is divided. Such being the case, the percentage of trunking can be increased by increasing the number of groups into which the subscribers' substations are divided, and by thus reducing the number of subscribers 80 in each group. With this arrangement there will still be ten trunk lines leading from the individual switches of each group of subscribers, making ten trunk lines for each fifty subscribers, and over these trunk lines 85 the calling subscribers can connect with any of the various first-selectors, depending upon which of the first-selectors are busy and which are idle. It is true, of course, that in order to increase the trunking from 90 ten to twenty per cent in the manner just described, it will be necessary to also increase the number of non-numerical trunking switches intermediate of the subscribers' individual switches and the first-selectors. 95 This, however, will obviously not cost as much as it would to double the number of first-selectors, which latter would be the only method by which the trunking could be increased from ten to twenty per cent in the 100 old system. In fact, there can be as many first trunk lines for each group of subscribers as there are subscribers in the group, and still the number of first-selectors and second-selectors and connectors will 105 remain the same, thus increasing the trunking facilities between the subscribers' telephone lines and the first-selectors, without

necessitating a corresponding increase in the number of numerical switches. In other words, with my improved arrangement there could be ten subscribers in each group, and 5 there could be ten trunk lines leading from the individual switches of each group of subscribers, these trunk lines terminating in the secondary or intermediate non-numerical trunking switches; and with this method 10 of trunking no calling subscriber would ever be delayed for want of a trunk line, and would always get a selector unless all of the numerical switches were in use, which would not be likely to happen. For practical purposes, however, an increase of from ten to 15 twenty per cent would ordinarily be found sufficient to preclude any calling subscriber from being delayed for want of a trunk line leading from his individual switch, as to 20 bring about such a condition in any group of fifty subscribers would require that all ten of the first trunk lines therefor be found busy at the same time, so that the eleventh calling subscriber would find no idle trunk 25 line. Increasing the percentage of trunking to this extent would only require an increase in the number of secondary or intermediate non-numerical switches, and would not require an increase in the number of numerical 30 switches. Consequently, as previously stated, my improved method of trunking affords ample opportunity for giving better trunking facilities between the subscribers' lines and the numerical switches, without 35 materially increasing the cost of the exchange as a whole.

To the foregoing and other useful ends, my invention consists in matters hereinafter set forth and claimed.

40 In the accompanying drawings Figures 1 and 2 show diagrammatically a portion of a telephone system embodying the principles of my invention. In said figures the calling subscriber's substation is shown at A and the called subscriber's substation at A'. These two substations are shown connected through the medium of automatic switches. As shown, the line of the substation A terminates in an individual line 45 switch C which may be termed a primary non-numerical or individual switch. At D is shown a second switch that is common to a number of subscribers' stations, such as the substation A, which substations, in the following, will be considered as belonging to one group. The switch D may be called a secondary non-numerical trunking switch. It will be understood, of course, that the system may comprise a number of groups 50 of subscribers' stations similar to the one to which reference is made. The line switches C of each of these groups of substations are controlled in this system by a master switch E. It is to be further 55 understood that the secondary non-numerical switches D are also arranged in groups, and that each of said secondary switch groups is controlled by a master switch F. In addition, the system is equipped with selector switches H of the general type disclosed in Letters Patent No. 815,321, granted 60 March 13, 1906, to Keith, Erickson & Erickson. These selector switches are also arranged in groups. The exchange is also provided with still further groups of selector switches I which are, more or less, a modified form of the selector switches H. The system also has connector switches K of the general type disclosed in Letters Patent No. 815,176, granted March 13, 1906, to Keith, Erickson & Erickson, but modified to an extent to adapt them to common battery purposes. The line switch C', it will be understood, is, of course, identical with the line switch C. As shown in the various drawings, the system is provided with a central battery B having its positive terminal preferably grounded at G. This battery is used for both operating and talking purposes.

65 Figs. 3 and 4, it will be seen, are enlarged and more complete diagrammatic views of the primary and secondary non-numerical switches C and D.

70 Fig. 3^a is a detail view of the master switch bank.

75 Fig. 5 shows diagrammatically the trunking arrangement used in the system between primary and secondary non-numerical switches, the primary switches being shown in the upper section of the drawing, and the secondary switches being shown in the lower section. In a ten thousand system there will be one hundred groups of primary switches P¹, P², P³, etc., comprising one hundred switches C in each group; but there will be only ten groups of secondary switches U, V, W, etc., comprising one hundred secondary switches D in each group. The groups of primary switches will extend from left to right, as shown, while the individual units or switches will be arranged from front to rear, one hundred deep. The groups of secondary switches will extend from left to right, as indicated, and the units or switches themselves will extend from front to rear, one hundred deep.

80 Figs. 6 and 7, taken together, show more particularly the arrangement of the switches, and show in addition the groups of trunk lines leading to the selector switches H with reference to the secondary switches U, V, W, etc.

85 Fig. 8 shows a special wiring arrangement between the primary and secondary switches, whereby if all the trunk lines leading from a certain group of secondary switches become busy, all the master switches in the exchange that are retaining their line 90

switches opposite said busy set of trunk lines are then caused to operate and advance their allotted line switches opposite the next set of trunk lines; and whereby afterwards all master switches are prevented from stopping opposite said busy group of trunk lines until one or more of the lines in said group become idle.

Figs. 9, 10, 11, 12, 13, 14 and 15 are detail views of the impulse-spring mechanism of the subscribers' substations.

The general method by which the central office switching apparatus is operated is as follows: Referring to Figs. 6 and 7, when the subscriber at sub-station A turns the dial for the first digit his individual line switch C is operated by a preliminary impulse transmitted over the rotary line conductor to seize a trunk line leading to a second line switch D. As soon as this second line switch is seized by the first line switch it operates to seize a trunk line and extend the calling subscriber's line conductors to a first-selector switch H. All these preliminary trunking operations take place when the subscriber rotates the dial forward for the first digit; but as the dial returns, the first-selector switch is then operated for the first digit. The turning of the dial for the second digit causes the second-selector switch I to select an idle connector-switch K, and the connector is in turn operated when the dial is turned for the last two digits.

The substations may be of any suitable or approved type. The substation A, in connection with which I have elected to illustrate my invention, comprises a receiver 2, a switch-hook 3 for controlling the substation circuits, which controlling operations are accomplished through the medium of any suitable means, such as the cam-arms 4, 5 and 6. As the switch-hook is lowered the cam-arm 5 momentarily presses the release springs 7, 8 and 9 into engagement whereby the substation line conductors may be grounded simultaneously. When the switch-hook is down the cam-arm 4 maintains a contact between the springs 10 and 11, thereby bridging the ringer 12 in series with the condenser 13 across the line. The substation ground circuit is normally broken between the ground springs 14 and 15 by the cam-arm 6; but when said springs are together ground potential is provided to the ground post 17, and to the release spring 7, as is usually the case in telephones of this type. The said substation comprises the usual transmitter 18, and the induction-coil 19 having the primary winding 20 and the secondary winding 21. Being an automatic substation it is provided with the usual vertical and rotary impulse springs 22 and 23. The vertical impulse spring 22 is provided with an oblique projection or lug 24 on the under side, with which the vertical impulse

teeth 25 are adapted to engage for intermittently driving the spring 22 onto the ground post 17. The rotary impulse spring 23 is provided with somewhat similar mechanism for driving the said rotary spring onto the ground post once when the dial is rotated in one direction, and once when rotated in the opposite direction. The said rotary impulse spring 23 has on its under side a V-shaped member 26 having two sides *c* and *d*; and there is, in addition, an auxiliary spring 27, which works in conjunction with said V-shaped member. As shown more clearly in Fig. 9, the auxiliary spring 27 is provided with a lower curved part *e* having the rear section 28 curving outwardly, as shown also in Figs. 10 to 15, inclusive. The front section 29 of said member *e* is designed to fall just below the apex of the V-shaped member 26, so that the rotary impulse tooth 30, when moved in the direction of the arrow in Fig. 10, will pass onto the curved member *e*, thus pressing the rotary impulse spring 23 onto the ground post 17 for a comparatively long time, and sending a comparatively long impulse to the line, as shown in Fig. 11. As the impulse wheel advances, the vertical impulse teeth 25 approach the lug 24 of the vertical impulse spring 22 (Fig. 11), and eventually the first tooth *f* that meets the lug 24 clears the said lug, as shown in Fig. 12, but not until after the rotary impulse tooth 30 clears the curved member *e*. As the impulse wheel continues to advance in the direction of the arrow in Fig. 12, the next impulse tooth will clear the projection 24, as shown in Fig. 13. Then when the impulse wheel is released, the vertical impulse spring 22 is carried into engagement with the ground post 17, in the manner indicated in Fig. 14; but as the impulse wheel nears its normal position the rotary impulse tooth 30 passes under the curved member *e* of the auxiliary spring 27 (Fig. 15), engaging the V-shaped member 26 directly and for a short time only, sending the ordinary impulse through the medium of the rotary impulse spring 23 to the line, after which the said member 26 is cleared, as shown in Fig. 10, as the impulse wheel reaches its normal position. The operations as thus described are repeated each time that the dial is operated, and the number of impulses produced through the medium of the vertical impulse spring 22 is accurately and definitely determined at each operation of the dial by the finger-hole which the subscriber selects on the dial. It should be stated that a suitable stop is, as is well known in the art, provided to always limit the rotation of the dial, which stop indicates when to release the dial. By referring to Fig. 1 it will be seen that the impulse springs 22 and 23 are electrically connected with the vertical and rotary line

conductors 31 and 32 that lead to the central office. Said substation is, of course, provided with a dial (not shown) which is secured to the shaft 33, together with the locking dog 34. Furthermore, there is a locking cam 35 that locks the dog 34 while the receiver is on the switch-hook, to prevent a rotation of the dial. For operating the impulse springs 22 and 23 the substation is provided with the impulse wheel 36 that is secured to the shaft 33, which impulse wheel carries on its periphery the so-called vertical impulse teeth 25 and one rotary impulse tooth 30, already mentioned. The said impulse teeth are so arranged that when the dial is drawn down the impulse spring 22 is not carried into contact with the ground post 17; but as the dial returns, first the vertical teeth engage the vertical impulse spring 22, and after they have completed their work the rotary impulse tooth 30 operates the rotary impulse spring 23. In this operation the subscriber's vertical line conductor 31 is first given a number of ground impulses, and then the rotary line conductor 32 is given one ground impulse. It will be seen that as long as the dial is out of normal position the construction is such that the dog 34 permits the primary circuit springs 37 and 38 to separate, thus preventing the impulses that are delivered to either line conductor from passing to the other. The means whereby a subscriber may signal a called subscriber comprises the push-button 39 which, when pressed, carries the spring 40 out of engagement with the contact point 41 and into engagement with the contact point 42, whereby the vertical line conductor 31 is grounded.

The individual or line switch C (Fig. 3) is of the same general form disclosed in my U. S. Patent No. 1,283,413, granted October 29, 1918. The said switch comprises, as shown in Fig. 3, a plunger 44, plunger arm 45, bridge-cut-off relay 46, trip magnet 47 and switch-release magnet 48, all of which are built about a switch-base or frame (not shown) of any suitable or approved character. The said switch-release magnet is provided with an armature 49 that is pivoted on a pin 50 which rises from the base of the switch. The said armature carries pivotally secured on its end a second armature 51 that is controlled by the trip magnet 47. The pin 52 about which the armature 51 oscillates is carried on the end of the armature 49. The plunger 44 is pivotally secured by the pin 53 to the plunger arm 45, which latter is in turn pivoted to a pin 54 that rises from the switch-frame. The lug 55 is stamped or pressed out of the side of the frame and is provided as a stop or rest for the armature 49. Upon the armature 51 is secured the catch spring 56 which is adapted to engage the end 57 of the plunger arm

45. Furthermore, the said line switch is provided with a bank of terminals, usually ten in number, only one of which is shown at Q, Fig. 3. As shown, the said terminal Q is moved from its true position with respect to the swing of the plunger 44, and the bushing 62 is correspondingly turned, all for the purpose of making the illustration clearer. The terminal Q comprises the springs 63 and 64, 65 and 66, 67 and 68, and 69 and 70. The said springs are normally disconnected from each other, but are driven into contact in the above-mentioned order when the plunger 44 operates. When the plunger 44 is in locked engagement with the plunger shaft 60, the notch 61 is in engagement with the flange or web of the shaft 60, and when in sliding engagement the hub rests in the position shown by the dotted lines in Fig. 3—that is, when the plunger shaft is operated the plunger 44 is not carried along with the locked plungers, but remains in the dotted position, the plunger shaft sliding upon the end 59. The general operation of the switch is as follows: The trip magnet 47 is energized by a preliminary impulse, and the armature 51 is attracted against the magnet cores. When the armature 51 is attracted the catch 56 slides out of contact with the end 57 of the plunger arm 45, and the said plunger arm 45, owing to the tension of the spring 58, moves about the pin 54 and thrusts the plunger 44 into the bank terminal Q, shown in Fig. 3; and when the trip magnet again de-energizes, the trip armature 51 falls against the end of the plunger arm 45. The switch is restored when the release magnet 48 becomes energized, whereby the armature 49 is attracted, and accordingly the trip armature 51 is moved upwardly until the catch 56 slides over the end 57; then when the release magnet 48 becomes de-energized the armature 49 returns to normal position and remains at rest against the stop 55. Furthermore, since the plunger arm 45 is now in engagement with the armature 51, the said plunger arm is also moved about the pin 54, whereby the plunger 44 is removed from the terminal Q. Also, since the plunger shaft has advanced one step, the hub 59 of the plunger 44 comes to rest in the position shown by the dotted line in Fig. 3, in sliding engagement with the plunger shaft 60; and as the said plunger shaft advances each time an idle trunk is seized, the plunger 44 is not advanced, but remains in this position opposite the trunk terminal from which it has just disengaged, since the slot 61 is not in engagement with the plunger shaft 60. After all the trunk lines have been successively seized, and the shaft 60 is released from its last position, said shaft then starts toward starting point or normal position and picks up the plunger 44, when the saddle of the said

shaft, over which the slot 61 normally rides, arrives at the position at which the plunger 44 was originally released—that is, the plunger passes into locked engagement with the 5 shaft when the slot 61 slips over the saddle of said shaft. From thence on the plunger 44 is carried by the shaft 60 until it is again released when another call is made. But if, after the plunger is released, and before the 10 shaft 60 returns to pick up said plunger, the switch C is again operated, the plunger 44 again engages the same terminal Q. Furthermore, the plunger arm 45 is provided with an extension or finger 100, so that when 15 the plunger 44 is tripped into a bank the contact spring 101 is then pressed into engagement with the spring 102, whereby an energizing circuit is closed through the bridge-cut-off relay 46. The cut-off relay 20 46 upon energizing operates to shift the spring 103 out of engagement with the spring 104 and into engagement with the spring 105. When the spring 103 is thus operated the springs 104 and 106 also 25 disengage.

The master switch E, which may be of any suitable or approved type, is provided for operating the plunger shaft 60, and for controlling certain circuits that will be 30 closed hereinafter. It comprises the following details: A motor magnet 71 for operating the ratchet wheel 72, which latter is designed for operating the plunger shaft 60, and a differential relay 73 for controlling the 35 energizing circuit of the motor magnet 71. Furthermore, a second relay 107 which controls the springs 108 and 109 is also provided for closing the energizing circuit of the motor magnet 71. The master switch also 40 has a bank O comprising two sets of individual contacts *a* and *b* and two common metallic segments 74 and 110, one for each set of individual contacts. The wiper 75 is adapted to remain in constant engagement 45 with the bank O, and to maintain one of the segments *a* in electrical connection with the common segment 74, and also to maintain one of the individual segments *b* in electrical connection with the common segment 50 110. A preferred arrangement of the master switch bank is shown in Fig. 3^a where the individual segments *a* and *b* are separated from their common segments by the insulating strips 111^a. It will be noticed that after 55 the wiper 75 passes over the segments from right to left and engages the last segments, then on the next step the wiper 75 passes from the said contacts on the extreme left to the contacts on the extreme right, but in 60 passing from one extreme position to the other the wiper 75 slides on the insulated member 113. It will be seen by referring to the drawings that the contacts on the extreme left are marked 112, and that the contacts on the extreme right are marked 84 65 and 282. It will further be observed that in Fig. 3 the wiper 75 is divided into two sections by suitable insulation, the extreme end being insulated from the remainder of the wiper, whereby the contacts *b* and the contacts *a* are maintained electrically separated. In Fig. 3^a, however, the wiper 75 is represented as being composed of two separate and distinct wipers. This provision is made 70 in order that the individual segments may not be brought into contact with the common segments, whereby some interference with the successful operations of the master switch might be experienced. The contacts *a* and *b* are the terminals of the conductors 80 over which guarding potentials are provided for operating the master switch E. The contacts *a* are allotted to the trunk-lines leading from the primary switches to the secondary switches, while the contacts *b* are allotted 85 individually to a group of trunk-lines leading from the secondary switches to the first-selector switches—that is, if all the first-selectors of a group are busy simultaneously, a guarding potential appears at a contact *b* 90 allotted to this group, and the master switch wiper 75, in passing over these contacts, produces no effect unless there is a guarding potential present, in which event the motor magnet is energized as usual. 95

The mechanical details of the secondary switch D, as well as the mode of operation, are very much the same as those of the primary switch C. It will be seen that the primary switch C is supplied with a release magnet 48 and a trip magnet 47, and with a cut-off relay 46, while the secondary switch D is only equipped with a magnet 99 that performs not only the functions of a release magnet, but also an additional function 100 which the release magnet 48 of the primary switch C does not perform. This magnet 99 of the switch D is designed to always remain energized during the operation of the switch. The magnet 99 serves both as a trip magnet 105 and as a release magnet; for when the said magnet is energized the armature 111 is attracted, and the plunger 97 on the arm 98 is in turn thrust into its switch bank. Now, when the magnet deenergizes, the armature 111 then returns to normal position, thereby returning the plunger to normal position. Thus, through the medium of the magnet 99, the plunger is thrust into the bank and then 110 withdrawn. The armature 111 is pivotally secured to the switch-frame (not shown) at the point 112^a, and at the other end the link 113 is pivotally secured at the point 114. The connecting link 113 is in turn pivotally secured at the point 115 to the plunger arm 98 which rotates about the point 116. By means of the spring 117, which is riveted to the plunger-arm 98, the plunger arm mechanism is restored to normal position 120 upon the deenergization of the magnet 99. 125

The plunger arm 98 is provided with a finger 118 which, when the plunger is operated, shifts the spring 119 out of engagement with the spring 120 and into engagement with the spring 121, as shown in Fig. 4. By this operation the magnet 99 is disconnected from the conductor 125 which leads to the motor magnet and is connected directly to the battery lead. It will be seen that the bank Q' 10 is similar to the bank Q of the primary switch C, Fig. 3.

The master switch F shown in Fig. 4 is very much like the master switch E shown in Fig. 3, with certain points of difference, 15 however—namely that the master switch F has no auxiliary relay, such as the auxiliary relay 107 of the master switch E, and the bank O' of the master switch F is a single bank and not a double bank as shown in Fig. 20 3. A motor magnet 122 is provided for operating the ratchet wheel 123 which in turn operates the plunger shaft 124. The relay 126 is provided for controlling the energizing circuit of the motor magnet 122. The 25 master switch bank O' comprises only one set of individual contacts and only one common metallic segment 127. The operation of the master switch F, on the whole, is the same as the operation of the master switch 30 E, and the description previously given in connection with the master switch E will be sufficient.

The selector switch H, as already stated, is a modified form of a well-known form of 35 selector switch. It is provided with a vertical magnet 128 and a rotary magnet 129, a release magnet 130 and a private magnet 131. The said private magnet, of course, controls the side switch wipers 132, 133, 134 40 and 135, and also the circuit of the vertical magnet 128 and release magnet 130, in the usual manner, by means of the springs 136, 137 and 138. The vertical movement of the switch shaft (not shown), and, therefore, of 45 the wipers 139, 140 and 141, is controlled by the vertical magnet 128, and the rotary movement by the rotary magnet 129. Included in the energizing circuit of the rotary magnet are the usual interrupter springs 142. The 50 operative magnets of the switch are controlled by the subscriber through the medium of the vertical and rotary relays 143 and 144, as is well known. Said relays have under their control the usual springs 145, 146 and 147. By means of the back-release 55 relay 148 the release of the switch H is brought about after the side switch has passed to third position.

The selector I is, as already stated, much 60 like the selector H. It is of the trunk-release type, in which the vertical and rotary line relays 149 and 150, acting conjointly, press the release springs 151 and 152 into contact, the former of which is connected to the trunk-release conductor and the latter

with the release magnet 153, whereby an energizing circuit is closed through the release magnet 153. The selector I is also provided with the vertical magnet 154, the rotary magnet 155 and the private magnet 156. 70 Unlike the private magnet of the selector switch H, the private magnet 156 of the selector I does not control the release magnet 153. The back-release relay 157 provides means whereby the selector switch may be 75 released after the side switch passes to third position.

In the connector switch K the vertical and 80 rotary line relays 158 and 159 may be operated to impart to the shaft wipers 160, 161 and 162 their vertical and rotary motions. While the side switch is in first position the vertical line relay 158 controls the vertical magnet 163, and when the side switch passes to second position the rotary magnet 164 85 comes under the control of the said relay; and similarly when the side switch passes to third position the ringer relay 165 is placed under the control of the vertical line relay 158. The connector rotary line relay 159, 90 as is well known, controls the private magnet 166, which latter in turn operates to shift the side switch wipers 167, 168, 169 and 170 from first to second position and from second to third position. The two line relays, 95 acting conjointly, provide means whereby the release magnet 171 may be energized to release the connector switch. The differential relay 172 controls the energizing circuit of the back-bridge relay 173, through which latter the called substation receives battery current for talking purposes. The said relay 173 upon energizing closes a circuit which in turn provides the calling substation with battery current for talking purposes. 100

The central office is provided with a suitable ringer generator R and a busy-signalizing machine M.

A clearer understanding of the principles of my invention may be had by following 110 the general operation of the apparatus when one subscriber calls another. Assume, for example, that the subscriber at substation A desires to call the subscriber at substation A' to which is allotted the line #2220. To call the number 2220 the subscriber at substation A raises his switch-hook and operates the calling device once, in the well-known manner, for each digit. When the dial is drawn down for the first digit a preliminary 115 impulse is, as already explained, transmitted over the rotary line conductor 32, which preliminary impulse energizes the trip magnet 47, whereby the non-numerical primary line switch C is operated to seize an idle 120 trunk line leading to a secondary non-numerical line switch D, which is in turn operated by the primary switch C to seize an idle trunk line leading to a first-selector switch H. The dial, in returning to normal position 125 130

for the first digit, operates the first-selector switch to establish connection with an idle trunk line leading to a second-selector I. The second-selector I, in a similar manner, is operated for the second digit to select an idle trunk line leading to a connector switch K. It will be understood, of course, that when the dial is turned for each digit a preliminary impulse is transmitted to the rotary line conductor, which impulse, if a selector H or I or a connector K is on the line, is received by the rotary line relay of the switch while the side switch is in first position. This rotary line relay, of course, energizes, but since the side switch is in first position such energizing is without effect, and the switch is not operated until the dial delivers the vertical impulses. The reason that the preliminary impulses are not effective in operating the side switch of the selectors H and I or the connector K is due to the fact that the side switch is locked in first position until the switch is given the first vertical step. Said preliminary impulses are effective only in operating the non-numerical switches. The impulses to the vertical line for the last two digits are directed toward the connector K, which operates to place its shaft wipers in connection with the contacts corresponding to the desired line. The preliminary impulse for operating the line switch C, which occurs when the calling subscriber rotates the dial forward for the first digit, is caused by the rotary impulse spring 23 being pressed against the ground post 17. As a result of this impulse the trip magnet 47 of the line switch C is energized by a flow of current from ground G' to the springs 14 and 15, ground post 17, impulse spring 23 to the rotary line conductor 32, conductor 174, cut-off relay springs 104 and 106 to the trip magnet 47, thence through said trip magnet to the conductor 175, springs 176^a and 87, through the winding of the motor magnet 71 to the battery lead 176, thence through battery B to ground G. Although this circuit includes the motor magnet 71, this magnet 71 does not operatively energize, since the magnet 47 is of much higher resistance than the magnet 71. As soon as the trip magnet 47 energizes, the armature 51 is attracted, and the plunger 44 is liberated and thrust into the bank terminal Q by the spring 58, assuming that the plunger 44 is opposite the terminal Q at the time. When the plunger 44 engages the bank terminal Q an energizing circuit is closed through the motor magnet relay 73, which in turn operates to close an energizing circuit through the motor magnet 71. The motor magnet then operates to advance all idle plungers that are in locking engagement with the shaft 60 to a position opposite the next idle bank terminal, similar to the terminal Q. The circuit through the relay 73 extends from ground G² through the wind- ing 177 of the relay 73, segment 74, wiper arm 75, segment 84, conductor 178, bank terminal springs 70 and 69, release magnet 48 to the battery lead 176, thence through battery B to ground G. Although this circuit includes the release magnet 48, the magnet 48 does not operatively energize, since the windings of the relay 73 are of a high resistance, while the winding of the release magnet is tact 84, over the following circuit: from gizing operates to place the springs 87 and 88 in contact, whereby a circuit is completed through the motor magnet 71 extending from ground G³ through the springs 88 and 87, motor magnet springs 85 and 86, through the motor magnet 71 to the battery lead 176, thence through battery B to ground G. The motor magnet 71 upon energizing attracts its armature 81, whereby the pawl 82 engages the ratchet wheel 72 and rotates the wheel one step.

When the armature 81 is attracted against the magnet cores the springs 85 and 86 disengage, thereby breaking the energizing circuit through the motor magnet. The cam 76 being in engagement with the pin 77 is operated to advance the plunger shaft 60 and all idle plungers that may be in normal or locked engagement with the said shaft one step and opposite another trunk terminal similar to the terminal Q, assuming the next succeeding trunk is idle. Consequently, the wiper 75 is carried from the contact point 84, which corresponds to the terminal Q, to the contact point 89, which latter corresponds to the terminal before which the advanced idle plungers are now resting. The effect of the movement of this wiper 75 over the contacts b need not be considered at present. Suppose that nine subscribers have called, and that the master switch has thus been operated nine steps, carrying the wiper 75 to the last contact point 112. Now, when the motor magnet 71 operates for the next step—when the tenth subscriber calls—the wiper 75 passes back and drops into engagement with the contact point 84, as already explained. If the first trunk is still busy the wiper 75 finds battery current on contact 84, and an energizing circuit is established through the differential relay 73, which in turn operates to close an energizing circuit through the motor magnet 71. The current through the said relay 73 flows from the said contact 84 through the wiper 75 to the common segment 74, through the winding 177 of the differential relay 73 to ground G². When the differential relay 73 attracts its armature the differential relay springs 87 and 88 are pressed into contact, thereby closing an energizing circuit for the motor magnet 71 from ground G³ through the said springs 88 and 87, through the motor magnet springs 85 and 86, motor magnet 71, thence to the battery lead 176, and through

battery B to ground G. The motor magnet then operates, as previously explained, to rotate the ratchet wheel 72 one step for advancing the plunger shaft 60 one step, and 5 the master switch bank wiper 75 one step also, into engagement with the second segment 89. The plunger shaft 60, when thus advanced one step, carries all idle plungers that are in engagement with the said shaft 10 to a position opposite the next bank terminal, as previously explained. If there should still be a guarding potential at the bank segment 89 of the master switch bank 15 the differential relay 73 will remain energized, whereby the energizing circuit through the motor magnet 71 is again completed when the motor magnet springs 85 and 86 again engage; and as a result the motor magnet 71 is again operated, whereby the 20 plunger shaft 60 and the master switch wiper 75 are advanced another step. This process continues as long as the wiper 75 continues to find segments with guarding potentials. As soon as an idle segment is found, however, 25 the energizing circuit through the differential relay 73 is broken, at which time the said relay in turn breaks the energizing circuit for the motor magnet 71, until the next subscriber makes a call. At the instant 30 that the plunger 44 enters the said bank terminal Q the following springs are pressed into contact: 63 and 64, 65 and 66, 67 and 68, and 69 and 70. Also, the springs 102 and 101 are pressed into contact by the finger 35 100 on the end of the plunger arm 45, whereby an energizing circuit is closed through the cut-off relay 46, said circuit extending from ground G⁴ through the springs 102 and 101, through the relay 46 to the battery lead 176, and through battery B to ground G. The engagement of the springs 101 and 102 establishes a guarding potential, by way of 40 the normal conductor 96, to the connector private bank contacts corresponding to the line that terminates in the line switch C, to prevent any subscriber from calling the said line after the calling subscriber at substation A operates his dial preparatory to making a call, as explained. The cut-off relay 46 upon 45 energizing operates to shift the spring 103 from the springs 104 and 106 and into engagement with the spring 105. By this operation the subscriber's vertical and rotary line conductors 31 and 32 are disconnected 50 from the trip magnet, and the vertical normal conductor 94 is connected with the vertical line conductor 31. The engagement of the bank springs 67 and 68 closes an energizing circuit through the trip magnet 99 of the secondary line switch D (Fig. 4), said circuit extending from ground G⁵ through the springs 68 and 67, conductor 93, through the winding of the magnet 99, springs 119 and 120, conductor 125, motor magnet relay 55 springs 179 and 180, motor magnet springs 60 181 and 182, through the winding of the motor magnet 122 to the battery lead 176, and through battery B to ground G.

The magnet 99 upon energizing operates the plunger 97, as explained, to seize an idle 70 trunk line leading to a first-selector switch H. Also, the closure of connection between the springs 69 and 70 establishes a guarding potential at the master switch bank contact 84, over the following circuit: From 75 battery B to the battery lead 176, thence through the release magnet 48 and springs 69 and 70 over the conductor 178 to the said contact point 84. This guarding potential 80 protects the seized trunk conductors 90, 91, 85 92 and 93 from being seized by other plungers, as already explained. The closure of connection between the springs 63 and 64 extends the calling subscriber's vertical line conductor 31 to the vertical trunk conductor 90 and to the bank spring 183 of the secondary switch D. The closure of contact between the springs 65 and 66 in a similar manner extends the subscriber's rotary line conductor 32 to the rotary trunk conductor 91 and to the bank spring 184 of the line switch D. It will be understood that the bank terminal Q, being the first bank terminal of the line switch bank, corresponds to the first segment 84 of the master switch 90 bank O and, therefore, to the trunk line the conductors 90, 91, 92 and 93 of which terminate in the secondary switch D. When the magnet 99 of the line switch D energizes, as 95 explained, the plunger 97 is thrust into the bank Q' and the spring 119 is shifted out of engagement with the spring 120 and into engagement with the spring 121, whereby 100 a new energizing circuit is established through the magnet 99. This circuit extends 105 from ground G⁵ at the line switch C through the springs 68 and 67, conductor 93, through the magnet 99 and springs 119 and 121 to the battery lead 176, and through battery B to ground G, thus forming a locking circuit for the said magnet, which circuit is 110 maintained as long as the line switch C remains in connection with the trunk line conductors 90, 91, 92 and 93. Of course, as long as the magnet 99 remains energized 115 the plunger 97 maintains the bank springs of the bank Q' in contact in the following order: 183 and 185, 184 and 186, 187 and 188, and 189 and 190. When the plunger 97 engages the bank terminal Q' an energizing 120 circuit is closed through the motor magnet relay 126, which in turn operates to close an energizing circuit through the motor magnet 122. The motor magnet then operates 125 to advance all idle plungers which are in locking engagement with the shaft 124 to a position opposite the next idle bank terminal, similar to the terminal Q'. The circuit through the relay 126 extends from ground G⁶ through the winding 191 of the relay 130

126, conductor 192, segment 127, wiper arm 193, segment 194, conductor 195, through the bank springs 190 and 189, conductor 92, through the bank springs 70 and 69 of the 5 switch C, through the trip magnet 48 to the battery lead 176, and through battery B to ground G. Although this circuit includes the release magnet 48 said magnet does not operatively energize, since the winding 191 of the relay 126 is of high resistance, while the winding of the release magnet 48 is comparatively low. The relay 126 upon energizing operates in the same manner as the relay 73 of the master switch E to close an 10 energizing circuit through the motor magnet 122 which in turn operates (as explained in connection with the motor magnet 71) to advance the plunger shaft 124 and all engaging or locked plungers one step to 15 a position opposite another trunk terminal similar to the terminal Q', assuming that the next trunk line is idle. Consequently, the wiper 193 is carried from the contact point 194 to the contact point 196. The closure 20 of contact of the springs 183 and 185 extends the calling subscriber's vertical line conductor 31 to the trunk conductor 197, and to the side switch wiper 132 of the first-selector switch H (Fig. 2). The closure of 25 contact of the springs 184 and 186, in a similar manner, extends the subscriber's rotary line conductor 32 to the rotary trunk conductor 198 which leads to the side switch wiper 133 of the selector H. The subscriber 30 has thus established connection with the first-selector H, and now when the dial rotates back for the first digit the first-selector H is operated. The first digit being 2 the spring 22 is pressed onto the ground post 17 twice. As a result, the vertical line relay 143 of the first-selector H is energized each 35 time by a flow of current from the substation ground G' through the springs 14 and 15 to the ground post 17, thence through the spring 22 to the vertical line conductor 31, line switch bank springs 63 and 64, vertical 40 trunk conductor 90, bank springs 183 and 185, conductor 197, side switch wiper 132 of the selector H, contact point 200, vertical line relay 143 to the battery lead 176, thence through battery B to ground G. Each time 45 that the vertical line relay 143 energizes, the line relay spring 145 is pressed onto the ground spring 146. The vertical magnet 128 is thereby energized, and the wipers 139, 140 and 141 of the selector H are raised to the second bank level, opposite the first contact of said level. The energizing circuit for the said vertical magnet 128 extends 50 from ground G' through the springs 146 and 145, private springs 137 and 138 to the vertical magnet 128, thence to the battery lead 176, and through battery B to ground G. The rotary impulse spring 23 is then 55 pressed onto the ground post 17 once, grounding the rotary line conductor 32 and energizing, therefore, the rotary line relay 144 of the selector H. The energizing current passes from ground G' to the rotary line conductor 32, thence it flows through the 60 line switch bank springs 65 and 66, rotary trunk conductor 91, bank springs 184 and 186, conductor 198, side switch wiper 133 of the selector H, contact point 201 to the rotary line relay 144, to the battery lead 176, 65 and through battery B to ground G. The rotary line relay 144 upon energizing presses the line relay spring 147 onto the ground spring 146, thereby establishing a circuit 70 through the private magnet 131 from ground G' through the springs 146 and 147 to the private magnet 131, and through the said magnet to battery lead 176, thence through battery B to ground G. The private magnet 75 upon energizing and de-energizing permits the selector side switch to pass from first to second position, permitting the side switch wipers 134 and 135 to engage the contact points 202 and 203, respectively. The closure of connection between the side 80 switch wiper 134 and the contact point 202 sets up an energizing circuit for the rotary magnet 129 from ground G' to the contact point 202, through the side switch wiper 134, interrupter springs 142, rotary magnet 95 129 to the battery lead 176, and thence through battery B to ground G. The said rotary magnet 129 then operates to rotate the wipers 139, 140 and 141 of the selector H into 100 engagement with the first contacts of the second level of the selector H, from which contacts it is assumed that the trunk line conductors 204, 205 and 206 lead to the second-selector I. If the first trunk is busy, however, and the wipers have to pass over 105 busy trunk lines, then as soon as the private wiper 141 engages the first grounded private bank contact point, the private magnet 131 again energizes, locking the side switch in 110 second position. The energizing circuit for said private magnet extends from the grounded terminal G of battery B through an occupying switch (not shown) to the private wiper 141, thence over the conductor 115 207 and through the back-release relay 148 to the side switch wiper 135, contact point 203, private magnet 131, thence through said magnet to the battery lead 176, and through battery B to ground G. The private magnet 131, when thus 120 energized, locks the side switch in second position and the wiper 134 in engagement with the contact point 202, whereby the rotary magnet 129 will be energized step by step until the wipers are carried beyond the last busy trunk line. At the instant that the private wiper leaves the last busy contact point the energizing circuit through the private magnet 131 is destroyed, and as a result 125 the selector side switch passes to third 130

position. If, however, there are no busy trunk lines, the rotary magnet 129 releases the side switch to third position as soon as the wipers are carried into engagement with the first trunk line. As soon as the side switch passes to third position, as stated, the subscriber's line conductors 31 and 32 are extended to the conductors 204 and 205, which in this case it is assumed lead to the selector switch I. The extension of the line occurs, of course, as soon as the side switch wipers 132 and 133 engage the contact points 208 and 209, respectively. Not only is the subscriber's line thus extended, but a guarding potential is established at the private wiper 141, when the side switch wiper 135 passes onto the ground contact point 210, for protecting the seized trunk line against interference by other calling subscribers. This guarding potential is established from ground G^o to the contact point 210, thence through the side switch wiper 135 and through the back-release relay 148, conductor 207 to the private wiper 141. It will be seen, of course, that the energizing circuit for the rotary magnet 129, to which reference has already been made, is destroyed when the idle trunk line is seized—that is, when the side switch wiper 134 leaves the contact point 202.

The second digit of the called number being 2 the calling subscriber again operates his dial accordingly, as a result grounding the vertical line conductor 31 when the spring 22 meets the ground post 17. The vertical line relay 149 of the switch I is, therefore, energized twice by a flow of current from the substation ground G' to the vertical line conductor 31, thence through the line switch bank springs 63 and 64 to the vertical trunk conductors 90 and 197, thence to the side switch wiper 132 of the selector H, contact point 208, vertical line shaft wiper 139, vertical trunk conductor 204, side switch wiper 211, vertical line relay 149 to the battery lead 176, thence through battery B to ground G. That is, when the vertical line conductor 31 is grounded for the second digit an energizing circuit is established through the vertical magnet 154 which operates to carry the shaft wipers 212, 213 and 268 step-by-step to a position opposite the bank terminals of the second level. When the rotary line conductor 32 is grounded after the vertical impulses the rotary line relay 150 is energized, whereby an energizing circuit is established through the private magnet 156, which in turn operates to release the side switch as described in connection with the selector H. When the switch I comes to rest it is assumed that the shaft wipers 212 and 213 stop in engagement with the trunk conductors 214 and 215, respectively, as shown,

whereby the calling subscriber's line conductors 31 and 32 are extended to the connector switch K. The ground impulses from the substation to the line conductors for the last two digits—namely the third and fourth—are effective in operating the connector K. 65 70

The third digit is called after the subscriber has established connection with the connector K by way of the trunk conductors 214 and 215. The subscriber rotates the dial, as described, for the third digit 2, thereby grounding the vertical and rotary line conductors 31 and 32, which causes the energization of the connector vertical and rotary line relays 158 and 159, and also of the differential relay 172. The energizing current 75 flows over the following path: from ground G' to the vertical line conductor 31, trunk conductors 90, 197, 204 and 214, through the winding of the vertical line relay 158 and winding 216 of the differential 80 coil 172 to the battery lead 176, thence through battery B to ground G. Each time the vertical line relay 158 is energized the line relay springs 217 and 218 are pressed into contact, and an energizing circuit is 85 established each time through the vertical magnet 163. The energizing of the differential relay 172 is of no consequence at this time. The energizing current through the vertical magnet 163 flows from ground G^o 90 95 to the springs 217 and 218, private magnet springs 219 and 220, side switch wiper 169 to the vertical magnet 163, to the battery lead 176, thence through battery B to ground G. 100

Each time that the vertical magnet 163 is energized it raises the shaft and wipers 160, 161 and 162 one step at a time until the said wipers are carried two steps and brought opposite the level in which are located the terminals of the line #2220. When the rotary line conductor 32 is grounded the rotary line relay 159 and differential relay 172 become energized through the following path: from ground G' to the rotary line conductor 32, trunk conductors 91, 198, 205 and 215, through the winding of the rotary line relay 159 and winding 221 of the differential relay 172 to the back-bridge relay springs 222 and 223, which are normally in contact, to the battery lead 176, thence through battery B to ground G. The energization of the rotary line relay 159 causes the springs 224 and 217 to come into contact, thereby completing a circuit through the private magnet 166. The path of the energizing circuit is from ground G^o , line relay springs 217 and 224, through the winding of the private magnet 166 to the back-bridge relay springs 222 and 223, to the battery lead 176, thence through battery B to ground G. The momentary energization of the private magnet 166 110 115 causes the release of the side switch from 120 125

first to second position, thus placing the side switch wipers 169 and 170 in contact with the points 225 and 226, respectively.

The last digit being naught, the subscriber 5 operates the dial as previously described, grounding the vertical line conductor 31 ten times and the rotary line conductor 32 once. The vertical and rotary line relays 158 and 159 are operated over the previously traced 10 circuits. However, when the line relay springs 217 and 218 engage, a circuit is then closed through the rotary magnet 164, instead of through the vertical magnet 163. The circuit may be traced from ground G¹⁰ 15 to the line relay springs 217 and 218, side switch wiper 169, contact point 225, through the rotary magnet 164 to the battery lead 176, thence through battery B to ground G. Each time that the rotary magnet is energized 20 the rotary armature is attracted and rotates the shaft carrying the wipers 160, 161 and 162 one step at a time until the said wipers are carried into engagement with the normal conductors 227, 228 and 229, the first 25 two of which lead to the line of the desired subscriber, whose number is 2220. The energization of the rotary line relay 159 for the last digit completes an energizing circuit through the private magnet 166 which now 30 operates with one of two results, namely the release of the side switch from second to third position, or the so-called busy-release of the connector if the called line is busy. Suppose the former result to occur and the 35 side switch to pass to third position, thus placing the side switch wipers 167, 168, 169 and 170 in contact with the points 230, 231, 232 and 233, respectively. When the side switch wiper 169 engages the contact point 40 232 the ringer relay 165 comes under the control of the vertical line relay 158 in the same manner in which the rotary magnet 164 comes under the control of the vertical line relay when the side switch passes from 45 first to second position. Furthermore, when the side switch passes to third position a guarding potential is established for the protection of the called line. This guarding potential extends from ground G¹¹ to the side 50 switch wiper 170, thence to the shaft wiper 162 that now engages the private contact of the called line. The said guarding potential at the private wiper 162, furthermore, causes a flow of current to be sent through 55 the bridge-cut-off relay 234 from the said private wiper 162 to the private normal conductor 229, to the bridge-cut-off relay 234, thence to the battery lead 176, and through battery B to ground G. The said relay upon 60 energizing operates to carry the spring 235 out of engagement with the spring 236 and into engagement with the spring 237. When the spring 235 leaves the spring 236 the springs 236 and 238 also disengage, thus dis-

connecting both the vertical and rotary line conductors 239 and 240 of the called substation from the trip magnet 241 of the line switch C'. When the spring 235 engages the spring 237 the vertical normal conductor 227 is extended to the vertical line conductor 70 239.

To signal the called subscriber the calling subscriber presses the signaling button 39, placing the spring 40 in contact with the substation ground G' and thereby energizing 75 the vertical line relay 158 from ground G' through the springs 14 and 15, contact point 42, spring 40, springs 37 and 38 to the vertical line conductor 31, thence over a path previously traced. When the vertical line 80 relay 158 becomes energized the differential relay 172 is also energized through the winding 216. The armature is attracted and the springs 242 and 243 are placed in contact, thereby completing the energizing 85 circuit through the ringer relay 165, said circuit extending from ground G¹⁰ through the springs 217 and 218, private magnet springs 219 and 220, side switch wiper 169, contact point 232, through the ringer relay 90 165, differential relay springs 243 and 242 to the battery lead 176, thence through battery B to ground G; and as a result the ringer relay becomes energized forcing the springs 244 and 245 into contact with the 95 ringer generator springs 246 and 247, respectively. As a result, ringing current is permitted to pass out on the line of the called subscriber, which current passes 100 through the substation ringer 248 and signals the subscriber. This signaling current passes from the generator R to the springs 246 and 244, side switch wiper 167, contact point 230, shaft wiper 160, normal conductor 227, springs 237 and 235, vertical 105 line conductor 239, condenser 249, ringer 248, springs 250 and 251 to the rotary line conductor 240, normal conductor 228, shaft wiper 161, contact point 231, side switch wiper 168, ringer relay springs 245 and 110 247 and back to the generator R. As soon as the calling subscriber releases his signaling button 39 the current through the vertical line relay 158 and differential relay 172 is interrupted, de-energizing the said 115 relays, whereby the ringer relay returns to normal position. As the called subscriber removes his receiver 252 from the switch-hook 253, the latter upon rising destroys the ringing circuit through the bells 248 at 120 the instant the springs 250 and 251 separate. The switch-hook also forces the primary circuit springs 254 and 255 into contact, closing a circuit through its own station that provides the transmitter 256 and the 125 primary winding 257 of the induction-coil 258 with current for talking purposes. The current for this circuit passes from ground

G¹¹ at the connector to the side switch wiper 170, to the winding 259 of the relay 173, ringer relay springs 260 and 245 to the side switch wiper 168, rotary line wiper 161, conductors 228 and 240, primary winding 257 of the induction-coil 258, transmitter 256, springs 254 and 255 to the vertical line conductor 239, springs 235 and 237, conductor 227, vertical line wiper 160, side switch wiper 167 to the winding 261 of the back-bridge coil 173, springs 230^a and 242 of the differential relay 172 to the battery lead 176, thence through battery B to ground G. The energizing current for this talking circuit, in passing through the coil 173, energizes said coil and causes the armature to close in contact the springs 222 and 262. At the instant these two springs 222 and 262 engage the calling subscriber is thereby provided with current for energizing its primary talking apparatus. The circuit in this case extends from ground G¹¹ to the side switch wiper 170, through the springs 262 and 222, through the winding 221 of the differential relay 172, rotary line relay 159, trunk conductors 215, 205, 198 and 91 to the rotary line conductor 32, primary winding 20 of the induction-coil 19, transmitter 18, springs 37 and 38 to the vertical line conductor 31, trunk conductors 90, 197, 204 and 214, vertical line relay 158, through the winding 216 of the differential relay 172, thence to the battery lead 176, and through battery B to ground G. It will be seen that the two windings 216 and 221 of the differential relay 172 are included in the circuit that provides the calling subscriber with talking current. These two windings are so arranged that when the current passes through them in this manner the differential relay 172 does not energize. Since the talking current flowing to the calling subscriber passes through the vertical and rotary line relays 158 and 159, these two relays, as soon as the said circuit is established, become energized and attract their respective armatures, thereby placing the trunk-release springs 263 and 264 in contact. This would result in the release of the connector were it not for the fact that the connection between the release magnet 171 and the non-grounded battery terminal is interrupted between the differential relay springs 243 and 242. Under these conditions the primary windings 20 and 257 of the substations A and A', respectively, are connected in series in a circuit shown in heavy lines in Figs. 1 and 2, through the condensers 265 and 266 at the connector. The receivers 2 and 252 of the two substations in question are each in series in a local circuit with their respective secondary windings 21 and 267 of their induction coils 19 and 258, and in the usual manner the two subscribers may communicate with

each other, since their primary circuits are charged with a suitable current from the central or common battery B, as already explained.

After the two subscribers have completed their conversation the front release occurs when the calling subscriber restores his receiver 2 to the switch-hook 3, thereby pressing the release springs 7, 8 and 9 into engagement, which engagement places the line conductors 31 and 32 in connection with the substation ground G'. The grounding of the rotary line conductor 32 produces a cessation of the flow of current through the rotary line relay 159 and the winding 221 of the differential relay 172. This is brought about by short-circuiting these two windings in series through ground. The short-circuit extends from ground G' to the rotary line conductor 32, trunk conductors 91, 198, 205 and 215 to the rotary line relay 159, winding 221 of the differential relay 172 to the springs 222 and 262, to the side switch wiper 170 and to ground G¹¹. The rotary line relay becomes de-energized, and the trunk-release spring 264 recedes from the spring 263, and since only the winding 216 of the differential relay 172 is receiving current, the said relay becomes operatively energized. The current-flow through the said relay extends from ground G' to the release springs 7, 8 and 9 to the vertical line conductor 31, trunk conductors 90, 197, 204 and 214, vertical line relay 158, winding 216 of the differential relay 172 to the battery lead 176, thence through battery B to ground G. The energization of the differential relay 172, as above, produces a de-energization of the back-bridge relay 173, when the springs 230^a and 242 disengage, which relay 173 upon restoring its armature to normal position permits the springs 222 and 262 to disengage, and the spring 222 to come in contact with the spring 223. The engagement of these springs 222 and 223 again completes an energizing circuit through the winding 221 of the differential relay 172, and in this way current passes through said winding in such a direction as to reinforce the winding 216, and, therefore, to maintain the springs 242 and 243 in contact. Simultaneously with the re-energization of the rotary line relay 159 of the connector, the trunk-release springs 263 and 264 engage, thus completing an energizing circuit through the release magnet 171 of the connector, in series with the back-release relay 157 of the second-selector I. This circuit extends from ground G¹² at the selector I through the side switch wiper 267^a and release relay 157, shaft private wiper 268, connector trunk-release springs 263 and 264, through the winding of the release magnet 171, differential relay springs 243 and 242 to the battery lead 176, 130

and through battery B to ground G. The connector release magnet 171 upon energizing operates in the usual manner to restore the shaft wipers 160, 161 and 162 and 5 the side switch to normal position. The release relay 157 being included in the above release circuit also energizes and operates to place the springs 270 and 271 in contact, whereby a series energizing circuit is established through the back-release relay 148 of 10 the selector H and the release magnet 153 of the selector I. This circuit extends from ground G⁹ through the side switch wiper 135, release relay 148, conductor 207, private 15 wiper 141, conductor 206, release relay springs 270 and 271, through the release magnet 153 to the battery lead 176, thence through battery B to ground G. The release magnet 153 upon energization attracts 20 its armature and remains in readiness to restore the switch I when the energizing circuit through the release magnet is broken. The release relay 148 upon energizing operates to close the springs 272 and 273 in contact, whereby an energizing circuit is established through the release magnet 130 of the selector H and the release magnet 48 of the line switch C. The circuit through the release magnet 130 extends from ground 25 G¹³ at the switch H through the springs 272 and 273 and the magnet 130, to the battery lead 176, thence through battery B to ground G. The circuit through the release magnet 48 of the line switch C extends from 30 ground G¹³ through the springs 272 and 273 to the conductor 274, bank springs 190 and 189, conductor 92, bank springs 70 and 69, through the winding of the release magnet 48 to the battery lead 176, and through battery 35 B to ground G. The release magnet 130 upon energizing attracts its armature and remains in readiness to release the selector switch H when the said magnet de-energizes. When the release magnet 48 (Fig. 3) energizes 40 the armature 49 is attracted, whereby the armature 51 of the trip magnet 47 is raised, and the catch 56 engages the terminal 57 of the plunger arm 45, remaining thus in readiness to restore the line switch when the release magnet 48 de-energizes. As soon as 45 the substation release springs 7, 8 and 9 separate, the energizing circuit of the rotary and vertical line relays 158 and 159 of the connector K is destroyed. As a result the 50 energizing circuit through the release magnet 171 and the back-release relay 157 is broken. Of course, when the release magnet 171 de-energizes it throws the side switch of the connector back to normal position, removes the locking mechanism from the 55 switch-shaft, and produces a complete restoration of the connector switch K. It will be evident, of course, that when the private wiper 162 of the connector leaves the contact 60 point on which it has been resting, the energizing circuit through the bridge-cut-off relay 234 of the switch C' is also broken, which relay, of course, permits the springs it controls to return to normal position, thus 65 restoring the line switch C' to the control of the subscriber A'. The de-energization of the back-release relay 157 of the selector I also causes the de-energization of the release magnet 153 of the selector I. The release magnet 153, upon de-energizing, operates to restore the side switch and switch shaft of the selector I to normal condition. The de-energization of the said back-release relay 157 also, of course, breaks the energizing circuit of the back-release relay 148 of the selector switch H, which relay in turn causes the de-energization of the release magnet 130 of said switch H, and the de-energization of the release magnet 130 causes the full restoration of the side switch, shaft and circuits of the selector H, exactly as the release magnet 153 of the switch I operates in its allotted switch. It will also be seen that the de-energization of the back-release relay 148 of the selector H causes the de-energization of the release magnet 48 of the line switch C. When the release magnet 48 of the line switch C de-energizes, the retracting spring 58, by the aid of the armatures 51 and 49, withdraws the plunger 44 from its operated position and causes it to engage with the plunger shaft 69, as a result destroying, of course, the energizing circuit of the cut-off relay 46 when the springs 102 and 101 disengage. Furthermore, the disengagement of the springs 101 and 102 removes the guarding potential from the connector bank, and the separation of the bank springs 69 and 70 removes the protecting potential from the contact 84 of the master switch bank O. Also, when the bank springs 67 and 68 disengage, the energizing circuit through the magnet 99 of the secondary switch D becomes broken, thereby 100 permitting this switch D to return to normal position. It will be seen, of course, that the restoring mechanism of the switch D is the same as that of the switch C, and that the spring 117, by the aid of the armatures 113 and 111, performs the same operation as do the spring 58 and armatures 51 and 49 of the switch C when the respective controlling magnets de-energize. When the plunger arm 44 of the primary line switch C is removed 105 from the bank terminal Q the calling subscriber's line conductors are disconnected from the secondary switch D, and when the plunger arm 97 is withdrawn from the bank Q' the trunk conductors 90, 91 and 92 are disconnected from the trunk conductors 197, 198 and 274 that lead to the first-selector H. When the release springs 7, 8 and 9 at the substation disengage, the calling subscriber thus restores all of the switching apparatus 110 which he originally brought into use. 130

Special attention is now called to Figs. 5, 6, 7 and Fig. 8. It has already been explained that Fig. 5 shows in a very general way the distribution of the switches and a 5 trunking arrangement from primary non-numerical switches to secondary non-numerical switches, and from the secondary non-numerical switches to first-selectors or first numerical switches. The groups of sub- 10 scribes' lines and their allotted line switches are shown, as already stated, at P^1 , P^2 , etc., Fig. 5. As shown, the line switches P^1 have a number of trunk lines common to them and used by them only. The line switches 15 P^2 have a similar provision, and so on for each of the groups. With the arrangement shown the multiple terminals u' have allotted to them the secondary non-numerical switch u'^x of the group U; the multiple terminals 20 v' of the same group P^1 have allotted to them the non-numerical secondary switch v'^x of the group V; and the multiple contacts w' of the group P^1 have allotted to them the secondary non-numerical switch w'^x of the 25 group W, and so on. A similar arrangement is carried out with respect to the multiple contacts of the group P^2 , which contacts have allotted to them a secondary non-numerical switch in each of the groups U, V, 30 and W, and so on, the contact u^2 taking the line switch u^{2x} , the contacts v^2 taking the line switch v^{2x} , the contacts w^2 taking the line switch w^{2x} , and so on. It will be seen, 35 therefore, that since for every group of primary non-numerical switches P^1 , P^2 , P^3 , etc., there is provided one set of secondary non-numerical switches u'^x , v'^x , w'^x , and so on, one in each of the secondary groups U, V, W, and so on, there will be found in each 40 group U, V, W, etc., as many secondary non-numerical switches u'^x , u^{2x} , u^{3x} , etc., as there are groups P^1 , P^2 , P^3 , etc. Consequently, in a ten thousand system made up of one hundred groups P^1 , P^2 , P^3 , etc., each 45 group U, V, W, and so on, will comprise one hundred secondary switches u'^x , u^{2x} , and so on. It will be seen, however, that a ten-thousand system will comprise one hundred groups P^1 , P^2 , P^3 , etc., but the maximum 50 number of groups U, V, W, etc., will be ten—that is, where a ten per cent trunking arrangement is employed. Of course, this percentage may be varied according to requirements. As indicated in said Fig. 5, the 55 bank contacts of the secondary switches U, V, W, etc., are multiplied in the same manner and in the same order as the bank contacts u' , v' , w' , etc., of the groups P^1 , P^2 , P^3 , P^4 , etc., are multiplied—that is, all the contacts in each perpendicular row are connected together; and it will be seen that each group U or V or W, etc., has allotted to it ten 60 trunk lines, each of which trunk lines terminate in a first-selector or first numerical switch, such as the first-selector H already 65 described. With the arrangement shown, and as already explained, the general mode of operation is as follows: It will be assumed, first, that the plungers of all the switches P^1 are opposite the first trunk line, which trunk line, of course, terminates in the secondary line switch u'^x , as shown; that the plungers of the line switches P^2 are opposite their first trunk line to which, as shown, is allotted the secondary line switch u^{2x} , and that the line switches P^3 are opposite their first trunk line, and so on. It will also be assumed that the line switches U are opposite their first trunk line which, as shown, terminates in the first-selector H. In a system in which 70 the switches are arranged as indicated in Fig. 5 it will be seen that if a subscriber of the group P^1 operates his line switch C, for example, to make a call, he will thereby seize the first trunk line and in turn operate the line switch D, which, as shown, is the first one of the series u'^x , u^{2x} , u^{3x} , and so on. The line switch C will, upon seizing the first trunk line, cause the master switch in that 75 group (which is represented at E in Fig. 3) to advance all the other line switches of this group P^1 to a position opposite the second trunk line. In a similar manner the line switch D, upon seizing the first trunk line, will cause the master switch of its group (shown at F in Fig. 4) to advance all other line switches in its group to a position opposite the second trunk line. Of course, it 80 is being assumed that all non-numerical switches, before the primary switch C called, 85 were in absolute normal condition, all plungers being in locked engagement with their plunger shafts. After the switches C and D have each operated, as described, to seize the first trunk line of its group, then if a 90 subscriber of the group P^2 makes a call he 95 will operate his primary switch and seize the first trunk line of the group P^2 , taking the secondary switch u^{2x} of the group U. This secondary switch u^{2x} will in turn operate and plunge in on the second trunk line 100 terminating in the second first-selector of the group U'. Of course, when the primary switch of the group P^2 operates, the master switch of that group will then advance all 105 other primary switches to a position opposite the second trunk. In a similar manner, the secondary switch u^{2x} causes the master switch of the group U to advance all 110 idle secondary switches to a position opposite the third trunk line. Again, if the next subscriber to call is in the group P^3 he will take the first trunk line of his group which, 115 as shown, terminates in the secondary switch u^{3x} of the group U. Therefore, it will at 120 once be apparent that if ten calls are made in this way—that is, one from group P^1 , one from group P^2 , one from group P^3 , one from group P^4 , and so on—the tenth subscriber 125 will seize the secondary switch u^{10x} which 130

will in turn seize the tenth trunk line leading to the tenth first-selector of the group U' . Then if it is assumed that none of the subscribers that have called have released before the subscriber of the group P^{11} (or of the eleventh group) makes a call he will not find a vacant trunk to the group U which he may use. In order to prevent such an occurrence I provide a special arrangement which operates as soon as the last and tenth trunk is seized, to operate all remaining master switches of the hundred groups P^1 , P^2 , P^3 , etc., that have not already operated to advance all their line switches opposite their second trunk lines. This general operation, however, will not occur if, before the tenth subscriber calls, one of the preceding nine has released. It will at once be apparent that the value of this general advancement of all line switches to a position opposite the second trunk line will put the V -group of secondary switches at the disposal of the succeeding subscribers who may call. This special arrangement to which I refer not only has the effect of throwing all master switches from a position opposite the busy-group U , but will also prevent any master switch from subsequently stopping opposite the said busy-group U , unless in the meantime one of the trunk lines of that group has become idle. Heretofore the arrangement in certain percentage systems has been such that each group of one hundred subscribers has had access to only one group of first-selectors, varying from ten to fifteen in number. In still other percentage systems a first-selector switch is allotted to each subscriber. But with this arrangement all the subscribers have access to all of the first-selectors in the system. This is a great improvement over the systems that have been heretofore proposed. My invention, however, is not limited to this arrangement, but if it becomes desirable I can divide the number of groups P^1 , P^2 , P^3 , P^4 , etc., in half—that is, instead of having one hundred groups P^1 , P^2 , P^3 , etc., I can have two sets of groups, fifty in each. This, of course, will call for twice as many secondary switches U , V , W , etc., and finally double the number of first-selectors U' , V' , W' , etc., in which case half of the subscribers would have access to half of the first-selectors in the system, and the other half to the other half of the first-selectors in the system. It will also be evident that the percentage of first-selectors to the number of subscribers is not necessarily limited, but may be varied as desired. Figs. 6 and 7 cover the same subject-matter as that represented in Fig. 5, the only difference being that the details of cabling are more clearly and precisely brought out. For example, a line switch C in the group P^1 (Fig. 6) is shown in connection with its bank terminals and the bank conductors leading therefrom. Furthermore, in these Figs. 6 and 7 the conductors 90, 91, 92 and 93 that lead from the bank terminals of the line switch P^1 are shown in certain sections in detail, while in other sections a single line is used to represent all of these conductors, and a number of similar lines coming from the groups P^1 , P^2 , P^3 , etc., running together in a still heavier line to represent a still larger cable. In Fig. 7 the line switch D is shown in the same manner that the line switch C is shown in Fig. 6, to illustrate more clearly how these bank terminals are wired up. Fig. 8 goes further into detail regarding the multiplying shown in Figs. 6 and 7, and illustrates more clearly the method by which the general movement of the master switches, previously described, is accomplished when all the trunks to one group of first-selectors U' (Fig. 5), for example, become busy. Also, in Fig. 8 a large number of line switch banks are shown, and the multiplying circuits necessary for accomplishing the features aforesaid are very clearly shown. In said Fig. 8 is indicated at C the line switch C of Fig. 3; but at Q the bank springs are arranged in a slightly different order, so that the circuits are made clearer and thus more easily understood. Furthermore, in said Fig. 3, reading from right to left, the order of the springs is 64, 66, 65, 63, 68, 69, 70 and 67, but in Fig. 8 the order has been changed as follows: reading upward, 66, 65, 64, 63, 68, 67, 69 and 70.

At D (Fig. 8) is represented the line switch D of Fig. 4 and at Q' is shown the bank. The arrangement of the springs, reading upward, is as follows: 186, 184, 185, 183, 187, 188, 189 and 190. At the left the groups P^1 , P^2 , P^3 , P^4 , etc., of Fig. 5 are represented by the master switch banks O , etc. Also, in Fig. 8 the method of multiplying the contacts of the lower sections b of the master switch banks is clearly shown. For example, the first contacts at the right are multiplied together, from which multiple a lead 283 runs to the spring 188 of the secondary switch bank Q' , which conductor is used for causing the forward movement of all master switches away from the group U , when all the trunks of said group are busy. In a similar manner, the second contacts from the right are multiplied together, and a lead 284 extends to the spring 285 of the secondary switch of the group V to take care of that group, the same arrangement being followed throughout the whole set of bank contacts b , as indicated. The method of connecting or wiring up the springs 188 and 187 of the various bank terminals Q' (see group U , for example) is as follows: The spring 188 of the first bank terminal Q' is connected to the trunk 283, and the spring 187 is permanently connected with the

spring 188 of the second bank terminal Q' ; also, the spring 187 of the second bank terminal is permanently connected with the spring 188 of the third bank terminal; likewise, the spring 187 of the third bank terminal is permanently connected with the spring 188 of the fourth bank terminal, and so on throughout the set of terminals Q' . The spring 187 of the last bank terminal is, however, as shown, connected to ground. The fact that it is this last spring that is connected to ground, and not the first spring 187, is indicated in Fig. 4 at the bank Q' by the dotted connection between ground G^{14} and the said first spring 187. It will be evident, then, that if the ten trunks of the group U are in use at the same time—that is, if ten banks Q' of the group U are put into use, the conductor 283 will be grounded, and a guarding potential thus transmitted to the first contacts of the various master switch banks O of the groups $P^1, P^2, P^3, \dots$, and as a result all relays 107 (Fig. 3) of the remaining master switches which happen to be on this contact will be energized, and the master switches caused to vacate this trunk. It will be seen that only one bank terminal Q is shown for each of the groups $P^1, P^2, P^3, \dots$, and by comparing Figs. 5 and 8 it will be seen that the bank terminal of the group P^1 shown in Fig. 8 corresponds to the bank terminal u' shown in Fig. 5. In group P^2 the bank terminal shown corresponds to the bank terminal v^2 of Fig. 5. In group P^3 the bank terminal shown corresponds to the bank terminal w^3 . In group P^5 the terminal shown is the bank terminal x^5 of Fig. 5. The arrangement shown in Fig. 8, of course, illustrates exactly what is shown more or less in Fig. 5, namely that if the master switches of groups $P^1, P^2, P^3, \dots$, are each resting opposite its first right-hand bank terminal (Fig. 8), the primary switches of the group P^1 will be opposite the first secondary switch u'^x of the group U; the primary switches of the group P^2 will be opposite the second secondary switch u^{2x} of the group U; the primary switches of the group P^3 will be opposite the third secondary switch u^{3x} of the group U, and so on. The first right-hand master switch bank contacts are, therefore, allotted to the group U of secondary switches. If all the master switches are opposite the second bank contacts, counting from the right, similar secondary switches will be covered by the groups $P^1, P^2, P^3, \dots$, in the group V—that is, the group P^1 will be covering the first secondary switch in the group V, the group P^2 covering the second secondary switch in the same group, the group P^3 covering the third secondary switch, and so on; and if the master switches are opposite the third contact, counting from the right, then the secondary switches of the group W will be

covered in the same manner, and so on. It is very evident, therefore, that if all the bank terminals Q' of the group U are put into use and the trunk 283 therefore connected to ground, as previously explained, so that the relays 107 of the master switches E of the various groups are energized, as previously explained, then all of the primary groups will be forced to vacate the secondary group U; and, also, if all of the banks of the group V come into use at the same time, the master switches of the primary groups will again be forced to vacate their positions opposite the secondary group V, and so on. In each of these cases an energizing circuit is established through all of the auxiliary relays 107 in multiple, which circuit is as follows: from ground G^{14} , for example, through the bank contacts 187 and 188 to the trunk 283 and to all of the master switch bank contacts in multiple, thence through the master switch wiper to the relays 107 and through battery B back to ground G^{14} , producing the effect already explained. This is a feature which, added to the other features, some of which are more or less known, makes it possible for the first-selectors or first numerical switches to be made common to all the subscribers.

The busy-release of the connector K follows as a result of the energization of the rotary line relay 159, if the called line is busy, as follows: The said relay 159 upon energizing energizes the private magnet 166, as previously described, which latter in turn 100 presses the springs 275 and 276 into contact. As soon as the said springs 275 and 276 engage, the release magnet 171 is then placed in connection with the private wiper 162 (since the side switch wiper 170 is now in 105 second position), which wiper 162 has been previously rotated onto a grounded contact. As a result a flow of current is sent through the release magnet 171 from the grounded private wiper 162 to the side switch wiper 170, to the private magnet springs 275 and 276 to the release magnet 171, differential relay springs 243 and 242, thence to the battery lead 176, and through battery B to ground G. The release magnet 171 upon 110 energizing releases the connector switch shaft and restores the connector side switch to its first position, returning the vertical magnet 163 to the control of the vertical relay 158. Therefore, if the subscriber at the calling substation (Fig. 1) presses the signaling button 39 and grounds the vertical line conductor 31, he operates the vertical line relay 158, which latter in turn 115 operates the vertical magnet 163. The vertical magnet armature raises the switch shaft so that the normal post arm 277 permits the switch shaft spring 278 to come into contact with the spring 279, and the busy-signaling current is sent to the calling subscriber's sta- 120 125

- tion from the busy-signaling machine M. The calling subscriber, upon hearing the busy-signal, will understand that the desired line is in service and will release the switching apparatus by hanging up his receiver. The vertical and rotary line conductors 31 and 32 are again grounded simultaneously over circuits that have been explained, whereby the vertical and rotary line relays 158 and 159 of the connector, together with the differential relay 172, are energized at the same time. The circuits for energizing said relays have already been pointed out. It will be evident, then, that the line relays 158 and 159 will carry the release springs 263 and 264 into engagement at the same time that the differential relay 172 carries the differential relay springs 242 and 243 into engagement, setting up, therefore, the energizing circuit for the release magnet 171 in series with the back-release relay 157 of the selector I, releasing the central office switches, as already explained in the foregoing.
- From the foregoing it will readily be seen that the number of trunk lines between the subscribers' lines and the trunks running to the first-selectors can be increased to any desired extent without the necessity of correspondingly increasing the number of first-selectors. If desired, the subscribers can be arranged in groups of fifty, with ten trunk lines leading from the individual switches of each group, thus increasing the trunking to twenty per cent, without increasing the number of first-selectors. Should it be found that even this is insufficient for some of the groups, the percentage of trunking can be still further increased, even to the extent of providing a trunk line for each subscriber, which would be the case were the subscribers arranged in groups of ten with ten trunk lines for each group. Should an arrangement of this kind be adopted, it will be seen that no calling subscriber would ever be delayed for want of a trunk line running to a first-selector, and that each calling subscriber would always obtain connection with the numerical switches, unless all of the first-selectors should be found busy at the same time. This, however, would not be likely to happen, and, furthermore, the average number of calls at the same time from any group of subscribers is ordinarily only a certain per cent of the total number of subscribers in the group, so that the number of trunk lines between the subscribers' individual switches and the secondary or non-numerical switches can be considerably less than the total number of subscribers. With my improved method of trunking, each first-selector is common to all of the subscribers in two or more of the groups into which the subscribers' substations are divided, and, as illustrated, each first-selector is common to all of the subscribers in the system. Consequently, the subscribers of a certain group do not invariably call into a group of first-selectors, but are afforded facilities for calling and obtaining connection with any of the different first-selectors, as well as with any of the different second-selectors and connectors. In other words, the numerical switches, or switches which perform trunking or connecting operations with direct reference to the different digits of the numbers of the different subscribers, are all common to all of the subscribers of the exchange. The non-numerical trunking switches, such as the switches D, are much simpler and more economical to manufacture and install and operate than the numerical switches, such as the first-selectors. Consequently, an increase in the trunking facilities between the subscribers' lines and the first-selectors, while necessitating an increase in the number of secondary or intermediate non-numerical switches, does not increase the cost of installation and maintenance as much as it would to increase the number of first-selectors, which latter are somewhat more costly to manufacture and maintain in good condition. In this way, as previously explained, I am enabled to increase the trunking facilities, and give better service in an automatic or semi-automatic exchange, and to do so without increasing the cost as much as would be necessary with the old arrangement. Other uses and advantages will be obvious to those skilled in the art.
- What I claim as my invention is:—
1. In a telephone system, a group of primary non-numerical line switches, a group of secondary non-numerical line switches, a plunger for each of the primary line switches, a plurality of bank terminals for each of said plungers, a master switch for said primary group for controlling the plungers thereof, and means operable by any one of said secondary non-numerical line switches for causing the master switch of the primary group to shift the plungers of the group from a position opposite one bank terminal to another.
  2. In a telephone system, a plurality of groups of primary line switches, a plunger for each of the line switches in said groups, a group of secondary line switches, a master switch for each of the said groups of primary line switches, a plurality of bank terminals for each of the plungers of the said primary line switches, and means operable by any one of the line switches of the secondary group for causing all of the master switches of the primary groups to operate simultaneously and cause the plungers of the line switches of their respective groups to move from a position opposite one bank terminal to another.

3. In a telephone system, a plurality of groups of primary switches, a plunger for each primary switch, a plurality of bank terminals for each plunger, a master switch 5 for each group for controlling the plungers thereof, a plurality of groups of secondary switches, and means operable by any secondary switch in any secondary group for causing all of the master switches of the primary 10 groups to operate and shift the plungers of the primary switches of their respective groups from a position opposite one bank terminal to another.
4. In a telephone system, a group of primary non-numerical switches, a master switch for said group, a secondary non-numerical switch, a motor mechanism for the master switch, a motor relay for controlling the said motor mechanism, and means under 15 the control of the secondary non-numerical switch for energizing said motor relay to cause a movement of the master switch and all of the primary switches, as set forth.
5. In a telephone system, a primary non-numerical switch, a secondary non-numerical switch, a trip magnet for the secondary switch, and an energizing circuit for 20 said magnet adapted to be set up by the primary switch and maintained until the said primary switch is released.
6. In a telephone system, a group of switches, a plunger for each of said switches, means for giving said plungers connective and selective movements, a master switch 25 for said group for controlling the selective movements of said plungers, a motor mechanism for said master switch, and a motor relay for controlling the motor mechanism of 30 said master switch, and for also preventing the connective movement of any plunger of said group while the master switch is operating.
7. In a telephone system, a group of switches, a plunger for each switch, means 40 for giving said plungers connective and selective movements, a master switch for said group for controlling the selective movements of said plungers, a motor mechanism for said master switch, a second group 45 of switches, a motor relay for controlling the motor mechanism of said master switch, and for also preventing the connective movement of any plunger controlled by the master switch, while said master switch is operating, said relay being allotted exclusively to and under the control of said first 50 group of switches, and a second relay also controlling the motor mechanism of the master switch, said second relay being allotted exclusively to and under the control of the second group of switches.
8. In a telephone system, a group of switches, a plunger for each switch, means 55 for giving said plungers connective and selective movements, a master switch for said 60
- group for controlling the selective movements of said plungers, a motor mechanism for said master switch, a second group of switches, a motor relay for controlling the motor mechanism of said master switch, and for also preventing the connective movement of any plunger controlled by the master switch while said master switch is operating, said relay being allotted exclusively to and under the control of the said first group of switches, a second relay for also controlling the motor mechanism of the master switch and allotted exclusively to the control of the second group of switches, and a bank for said master switch comprising two 75 sets of contacts, one set for controlling the energizing circuit of the said first relay, and the other set for controlling the energizing circuit of the said second relay, as set forth.
9. In a telephone system, a secondary non-numerical switch comprising a plunger, said plunger adapted for connective and selective and disconnecting movements, a master switch for controlling the selective movements, and a magnet for controlling the connective and disconnecting movements.
10. A telephone exchange system comprising subscribers' lines divided into a plurality of groups, an automatic trunking switch common to all of the subscribers' lines in all 95 of said groups, said switch adapted to perform a trunking operation in accordance with the first digit of any called number, and suitable means for trunking and completing the connection in accordance with the other digits of the called number.
11. A telephone exchange system comprising subscribers' lines divided into a plurality of groups, a first-selector and a second-selector and a connector, said first-selector being common to all of the subscribers' lines 105 in all of said groups.
12. A telephone exchange system comprising subscribers' lines divided into a plurality of groups, a plurality of first-selectors 110 less in number than the subscribers' lines, and suitable means for extending connection from the first-selectors to the called subscribers' lines, each of said first-selectors being common to all of the subscribers' lines 115 in all of said groups.
13. A telephone exchange system comprising subscribers' lines divided into groups, first-selectors, automatic means for trunking the subscribers' lines into connection with 120 said first-selectors, and suitable means for extending connection from the first-selectors to the called subscribers' lines, said first-selectors being each common to all of the subscribers' lines in all of said groups.
14. A telephone exchange system comprising subscribers' lines divided into groups, individual non-numerical trunking switches for said subscribers' lines, first-selectors, non-numerical trunking switches for auto- 125

matically extending connection from the subscribers' individual switches to the first-selectors, and suitable means for extending connection from the said first-selectors to the called subscribers' lines.

15. A telephone exchange system comprising subscribers' lines divided into groups, automatic numerical switches comprising or including selectors and connectors, all of which numerical switches are common to all of the subscribers of the different groups for calling any number, said numerical switches as a whole constituting the means for trunking and connecting in accordance with all of the digits of any called number, and suitable means for extending connection from calling subscribers' lines to said numerical switches.

16. A telephone exchange system comprising a trunking switch provided with a bank of subscribers' line and trunk terminals, a plunger adapted to cooperate with said bank in connecting the subscriber's line with any trunk, a magnet for actuating said plunger, and means for keeping the magnet energized to maintain the plunger in operative position.

17. A telephone exchange system comprising an automatic trunking switch provided with a bank of terminals, a plunger adapted to cooperate with said bank in closing trunk connections, a magnet for actuating said plunger, and means for keeping the magnet energized to maintain the plunger in operative position.

18. A telephone exchange system comprising a trunking switch provided with a bank of terminals, a plunger adapted to cooperate with said bank in closing trunk connections, an electromagnet, an armature for said magnet, a connection between the armature and the plunger, means for keeping the magnet energized to retain the plunger inoperative position, and a spring for retracting the plunger when the magnet is de-energized.

19. A telephone exchange system comprising a bank of terminals, a plunger adapted to cooperate with said bank, an arm on which said plunger is mounted, an electromagnet, an armature for said magnet, a link connecting said armature with said arm, a spring secured to said arm, and a connection between said spring and said link, said spring tending normally to retract the plunger and armature.

20. A telephone exchange system comprising subscribers' lines divided into a plurality of groups, an automatic trunking switch common to all of the subscribers' lines in all of said groups, said switch having vertical motion to select divisions of the exchange and rotary motion to connect with an idle trunk-line, and adapted to perform a trunking operation in accordance with the first digit of any called number, and suitable means for trunking and completing the con-

nection in accordance with the other digits of the called number.

21. In a telephone exchange system, the combination of the following mentioned elements, to-wit:—subscribers' lines divided into a plurality of groups, a first-selector and a second-selector and a connector, said first-selector being common to all of the subscribers' lines in all of said groups, said connector having vertical motion to select divisions of the exchange and rotary motion to connect with an idle line.

22. A telephone exchange system comprising subscribers' lines divided into a plurality of groups, a plurality of first-selectors less in number than the subscribers' lines, having vertical motion to select divisions of the exchange and rotary motion to connect with an idle trunk-line, and suitable means for extending connection from the first-selectors to the called subscribers' lines, each of said first-selectors being common to all of the subscribers' lines in all of said groups.

23. A telephone exchange system comprising subscribers' lines divided into groups, first-selectors having vertical motion to select divisions of the exchange and rotary motion to connect with an idle trunk-line, automatic means for trunking the subscribers' lines into connection with said first-selectors, and suitable means for extending connection from the first-selectors to the called subscribers' lines, said first-selectors being each common to all of the subscribers' lines in all of said groups.

24. A telephone exchange system comprising subscribers' lines, automatic numerical switches less in number than the subscribers' lines, having vertical motion to select divisions of the exchange and rotary motion to connect with an idle trunk-line, individual non-numerical switches for the subscribers' lines, and automatic non-numerical switches for extending connection directly from the subscribers' individual switches to the said numerical switches, said last-mentioned non-numerical switches being less in number than the subscribers' lines.

25. A telephone exchange system comprising subscribers' lines divided into groups, individual non-numerical trunking switches for said subscribers' lines, first-selectors having vertical motion to select divisions of the exchange and rotary motion to connect with an idle trunk-line, non-numerical trunking switches for automatically extending connection from the subscribers' individual switches to the first-selectors, and suitable means for extending connection from the said first-selectors to the called subscribers' lines.

26. A telephone exchange system comprising subscribers' lines divided into groups, automatic numerical switches comprising or including selectors and connectors having vertical motion to select divisions of the exchange

and rotary motion to connect with an idle trunk-line, all of which numerical switches are common to all of the subscribers of the different groups for calling any number, said numerical switches as a whole constituting the means for trunking and connecting in accordance with all of the digits of any called number, and suitable means for extending connection from calling subscribers' lines to said numerical switches.

27. In a trunking system, subscribers' lines divided into groups and an exchange divided into divisions comprising a plurality of subscriber's groups, first-selectors having vertical motion to select divisions of the exchange, and rotary motion to connect with an idle trunk-line in the division, and means whereby said selectors are made common to all of the subscribers' lines, substantially as shown and described.

28. In a telephone system in which the subscribers are divided and sub-divided, first-selectors each of which is common or accessible to the subscribers of the different sub-divisions, and means for completing connection from any operative first-selector to the called subscriber's line, each division representing a different thousand, and each sub-division representing a different hundred.

29. In a telephone system in which the subscribers' lines are divided into groups, means including a first-selector for extending connection from a calling subscriber's line to a called subscriber's line, common or accessible to the subscribers of a plurality of said groups, each group representing a different hundred.

30. In a telephone system, first-selectors, and means by which a plurality of successive non-numerical automatic trunking operations are necessary to enable any calling subscriber to reach any first-selector.

31. In a telephone system in which the subscribers are divided and sub-divided, selectors and connectors, and automatic trunking means whereby any subscriber of any division or sub-division may reach any selector or connector in the exchange, and cause the operation thereof, to extend connection in the direction of the called subscriber.

32. In a telephone system, a plurality of automatic trunking switches each having only a single level of trunk terminals, a first selector, and means for successively operating said switches to reach said first-selector.

33. In a telephone system, the combination of first selectors, means for controlling said selectors in accordance with the first digit of any called number, switches for automatically selecting idle selectors, and means for automatically selecting idle switches.

34. In a telephone system, a plurality of groups of trunk-selecting switches, trunk

lines leading out of said groups, trunk lines leading into said groups, means for selecting and seizing an idle trunk extending into said groups, and means for preventing the seizure of an idle trunk leading into a particular group when all the trunk lines leading out of said group are in use.

35. In a telephone system, a plurality of groups of non-numerical trunking switches, trunk lines leading out of said groups, trunk lines leading into said groups, automatic means for selecting and seizing an idle trunk extending into said groups, and means for preventing the seizure of an idle trunk leading into a particular group when all the trunk lines leading out of said group are in use.

36. In a telephone system, a plurality of groups of primary non-numerical trunking switches, a plurality of groups of secondary non-numerical trunking switches, trunk lines leading from the primary groups into the secondary groups, trunk lines leading out of the secondary groups, the number of trunk lines leading into each secondary group being greater than the number of trunk lines leading out of the group, and means for preventing the seizure of an idle trunk line leading into a particular secondary group when all the trunk lines leading out of said group are in use.

37. In a telephone system, subscribers' lines, non-numerical trunking switches common to a plurality of said lines, progressively movable means individual to the line and controlled from the substation on a calling one of said lines for selecting an idle one of said trunking switches, and means for completing a talking connection extending from the calling line through the selected non-numerical trunking switch to the called line.

38. In a telephone system, subscribers' lines, non-numerical trunking switches common to a plurality of said lines, progressively movable means individual to the line and controlled from the substation on a calling one of said lines for selecting an idle one of said trunking switches, means for operating the selected trunking switch, and means including a numerical switch for completing a talking connection from the calling line through the operated trunking switch to a called line.

39. In a telephone system, a line, a switch individual to said line, trunks for said switch, said switch having means controlled over the line circuit to extend a connection to one of said trunks, a second switch individual to the connected trunk, trunks for said second switch, said second switch having means automatically responsive to the seizure of the first trunk to extend a connection to one of said second trunks.

40. In a telephone system, a main switch,

an auxiliary switch accessible thereto, a line accessible to said auxiliary switch, a guarding potential circuit, and means for applying a potential to said circuit for making said line busy to the auxiliary switch and for making said auxiliary switch busy to the main switch, while said auxiliary switch is idle.

41. In a telephone system, a main switch, an auxiliary switch accessible thereto, a line accessible to said auxiliary switch, a guarding potential circuit allotted to said line, and means for applying a potential to said circuit making said line busy to the auxiliary switch and for making said auxiliary switch busy to the main switch, while said auxiliary switch is idle.

42. In a telephone system, a main switch, means for controlling the trunking operations of said switch, an auxiliary switch accessible thereto, a line accessible to said auxiliary switch, a circuit and means for applying a potential to said circuit for making said line busy to the auxiliary switch and for making said auxiliary switch busy to the main switch through the medium of said trunk controlling means for the first switch.

43. In a telephone system, a main switch, means for controlling the trunking operations of said switch, an auxiliary switch accessible thereto, a line accessible to said auxiliary switch, a guarding potential circuit allotted to said line, and means for applying a potential to said circuit for making said line busy to the auxiliary switch and for making said auxiliary switch busy to the main switch through the medium of said trunk controlling means for the first switch.

44. In a telephone system, a main selector switch, means for controlling the selecting operations of said switch, an auxiliary switch accessible thereto, a line accessible to said auxiliary switch, a guarding potential circuit, and means for applying a potential to said circuit for making said line busy to the auxiliary switch and for making said auxiliary switch busy to the main switch through the medium of said trunk controlling means for the first switch.

50 45. In a telephone system, a main selector switch, means for controlling the trunking operations of said switch, an auxiliary switch accessible thereto, a line accessible to said auxiliary switch, a guarding potential circuit allotted to said line, and means for applying a potential to said circuit for making said line busy to the auxiliary switch and for making said auxiliary switch busy to the main switch through the medium of said trunk controlling means for the first switch.

46. In a telephone system, a main switch, means for controlling the trunking operations of said switch, an auxiliary switch accessible thereto, a line accessible to said aux-

iliary switch, a guarding potential circuit, means for applying a potential to said circuit for making said line busy to the auxiliary switch and means for making said auxiliary switch busy to said main switch through the medium of said trunk controlling means for the first switch, while said auxiliary switch is idle.

47. In a telephone system, a main switch, means for controlling the trunking operations of said switch, an auxiliary switch accessible thereto, a line accessible to said auxiliary switch, a circuit allotted to said line, means for applying a potential to said circuit for making said line busy to the auxiliary switch and means for making said auxiliary switch busy to said main switch through the medium of said trunk controlling means for the first switch, while said auxiliary switch is idle, said second means comprising a guarding potential circuit allotted to said auxiliary switch. 75
80
85

48. In a telephone system, a main selector switch, means for controlling the selecting operations of said switch, an auxiliary switch accessible thereto, a line accessible to said auxiliary switch, a guarding potential circuit, means for applying a potential to said circuit for making said line busy to the auxiliary switch and means for making said auxiliary switch busy to said main switch through the medium of said trunk controlling means for the first switch while the auxiliary switch is idle.

49. In a telephone system, a main selector switch, means for controlling the selecting operations of said switch, an auxiliary switch accessible thereto, a line accessible to said auxiliary switch, a circuit, means for applying a potential to said circuit for making said line busy to the auxiliary switch and means for making said auxiliary switch busy to said main switch through the medium of said trunk controlling means for the first switch, while said auxiliary switch is idle. 100
105
110

50. In a telephone system, a main selector switch, means for controlling the selecting operations of said switch, an auxiliary switch accessible thereto, a line accessible to said auxiliary switch, a circuit allotted to said line, means for applying a potential to said circuit for making said line busy to the auxiliary switch and means for making said auxiliary switch busy to said main switch through the medium of said trunk controlling means for the first switch, while said auxiliary switch is idle. 115 120

51. In a telephone system, a series of main switches, auxiliary switches accessible thereto, lines accessible to said auxiliary switches, circuits and means for applying a potential to said circuits for making all of said lines busy to the auxiliary switches and for making said auxiliary switches busy 125 130

to the series of switches, while the auxiliary switches are idle.

52. In a telephone system, a series of main switches, auxiliary switches accessible thereto, lines accessible to said auxiliary switches, circuits allotted to said lines, and means for applying a guarding potential to said circuits for making all of said lines busy to the auxiliary switches and for making said auxiliary switches busy to the series of main switches, while the auxiliary switches are idle.

53. In a telephone system, a series of main switches, means for controlling the trunking operations of said switches, auxiliary switches accessible thereto, lines accessible to said auxiliary switches, circuits, and means for applying a potential to said circuits for making all of said lines busy to the auxiliary switches and for making said auxiliary switches busy to the series of switches through the medium of said trunk controlling means for the first series of switches.

54. In a telephone system, a series of main switches, means for controlling the trunking operations of said switches, auxiliary switches accessible thereto, lines accessible to said auxiliary switches, circuits allotted to said lines, and means for applying a potential to said circuits for making all of said lines busy to the auxiliary switches and for making said auxiliary switches busy to the series of switches through the medium of said trunk controlling means for the first series of switches while the auxiliary switches are idle.

55. In a telephone system, a series of main selector switches, means for controlling the selecting operations of said switches, auxiliary switches accessible thereto, lines accessible to said auxiliary switches, circuits, and means for applying a potential to said circuits for making all of said lines busy to the auxiliary switches and for making said auxiliary switches busy to the series of switches through the medium of said trunk controlling means for the first series of switches while said auxiliary switches are idle.

56. In a telephone system, a series of main selector switches, means for controlling the selecting operations of said switches, auxiliary switches accessible thereto, lines accessible to said auxiliary switches, circuits allotted to said lines, and means for applying a potential to said circuits for making all of said lines busy to the auxiliary switches and for making said auxiliary switches busy to the series of switches through the medium of said trunk controlling means for the first series of switches while said auxiliary switches are idle.

57. In a telephone system, a series of main

switches, auxiliary switches accessible thereto, lines accessible to said auxiliary switches, circuits, means for applying a potential to said circuits for making all of said lines busy to the auxiliary switches and means for making said auxiliary switches busy to said series of main switches, while said auxiliary switches are idle.

58. In a telephone system, a series of main switches, auxiliary switches accessible thereto, lines accessible to said auxiliary switches, circuits allotted to said lines, means for applying a potential to said circuits for making all of said lines busy to the auxiliary switches and means for making said auxiliary switches busy to said series of main switches, while the auxiliary switches are idle.

59. In a telephone system, a series of main switches, auxiliary switches accessible thereto, lines accessible to said auxiliary switches, guarding potential circuits, means for making all of said lines busy to the auxiliary switches and means for applying a potential to said circuits for making said auxiliary switches busy to said series of main switches, while the auxiliary switches are idle.

60. In a telephone system, a series of main switches, auxiliary switches accessible thereto, lines accessible to said auxiliary switches, circuits allotted to said auxiliary switches, means for making all of said lines busy to the auxiliary switches and means for applying a potential to said circuits for making said auxiliary switches busy to said series of main switches, while the auxiliary switches are idle.

61. In a telephone system, a series of main switches, auxiliary switches accessible thereto, lines accessible to said auxiliary switches, means for making all of said lines busy to the auxiliary switches and means for making said auxiliary switches busy to said series of main switches while said auxiliary switches are idle, said first means comprising guarding potential circuits, and second means each comprising a guarding potential circuit.

62. In a telephone system, a series of main switches, auxiliary switches accessible thereto, lines accessible to said auxiliary switches, means for making all of said lines busy to the auxiliary switches and means for making said auxiliary switches busy to said series of main switches while said auxiliary switches are idle, said first means comprising a guarding potential circuit allotted to each line, and said second means comprising a guarding potential circuit allotted to each auxiliary switch.

63. In a telephone system, a series of main switches, means for controlling the trunking operations of said series of main

- switches, auxiliary switches accessible thereto, lines accessible to said auxiliary switches, means for making all of said lines busy to the auxiliary switches and means for making said auxiliary switches busy to said series of main switches while the auxiliary switches are idle through the medium of said trunk controlling means for the first series of switches. 65
64. In a telephone system, a series of main switches, means for controlling the trunking operations of said series of main switches, auxiliary switches accessible thereto, lines accessible to said auxiliary switches, circuits, means for applying a potential to said circuits for making all of said lines busy to the auxiliary switches and means for making said auxiliary switches busy to said series of main switches through the medium of said trunk controlling means for the first series of switches, while the auxiliary switches are idle. 70
65. In a telephone system, a series of main switches, means for controlling the trunking operations of said series of main switches, auxiliary switches accessible thereto, lines accessible to said auxiliary switches, a circuit allotted to each line, means for applying a potential to said circuits for making all of said lines busy to the auxiliary switches and means for making said auxiliary switches busy to said series of main switches while the auxiliary switches are idle through the medium of said trunk controlling means for the first series of switches. 75
66. In a telephone system, a series of main switches, means for controlling the trunking operations of said series of main switches, auxiliary switches accessible thereto, lines accessible to said auxiliary switches, circuits, means for making all of said lines busy to the auxiliary switches and means for applying a potential to said circuits for making said auxiliary switches busy to said series of main switches while the auxiliary switches are idle through the medium of said trunk controlling means for the first series of switches. 80
67. In a telephone system, a series of main switches, means for controlling the trunking operations of said series of main switches, auxiliary switches accessible thereto, lines accessible to said auxiliary switches, a guarding potential allotted to each line, means for applying a potential to said circuits for making all of said lines busy to the auxiliary switches and means for making said auxiliary switches busy to said series of main switches through the medium of said trunk controlling means for the first series of switches, while the auxiliary switches are idle. 85
68. In a telephone system, a series of main switches, means for controlling the trunking operations of said series of main switches, auxiliary switches accessible thereto, lines accessible to said auxiliary switches, means for making all of said lines busy to the auxiliary switches and means for making said auxiliary switches busy to said series of main switches through the medium of said trunk controlling means for the first series of switches while said auxiliary switches are idle. said first means comprising guarding potential circuits, and second means each comprising a guarding potential circuit. 90
69. In a telephone system, a series of main switches, means for controlling the trunking operations of said series of main switches, auxiliary switches accessible thereto, lines accessible to said auxiliary switches, means for making all of said lines busy to the auxiliary switches and means for making said auxiliary switches busy to said series of main switches through the medium of said trunk controlling means for the first series of switches while said auxiliary switches are idle, said first means comprising a guarding potential circuit allotted to each line, and said second means comprising a guarding potential circuit allotted to each auxiliary switch. 95
70. In a telephone system, a series of main selector switches, means for controlling the selecting operations of said series of main switches, auxiliary switches accessible thereto, lines accessible to said auxiliary switches, means for making all of said lines busy to the auxiliary switches and means for making said auxiliary switches busy to said series of main switches while the auxiliary switches are idle through the medium of said trunk controlling means for the first series of switches. 100
71. In a telephone system, a series of main selector switches, means for controlling the selecting operations of said series of main switches, auxiliary switches accessible thereto, lines accessible to said auxiliary switches, a guarding potential circuit, means for applying a potential to said circuit for making all of said lines busy to the auxiliary switches and means for making said auxiliary switches busy to said series of main switches through the medium of said trunk controlling means for the first series of switches, while the auxiliary switches are idle. 105
72. In a telephone system, a series of main selector switches, means for controlling the selecting operations of said series of main switches, auxiliary switches accessible thereto, lines accessible to said auxiliary switches, a guarding potential circuit allotted to each line, means for applying a potential to said circuits for making all of said lines busy to the auxiliary switches and means for mak- 110

- 120
- 125

ing said auxiliary switches busy to said series of main switches through the medium of said trunk controlling means for the first series of switches, while the auxiliary switches are idle.

73. In a telephone system, a series of main selector switches, means for controlling the selecting operations of said series of main switches, auxiliary switches accessible thereto, lines accessible to said auxiliary switches, guarding potential circuits, means for making all of said lines busy to the auxiliary switches, and means for applying a potential to said circuits for making said auxiliary switches busy to said series of main switches through the medium of said trunk controlling means for the first series of switches, while said auxiliary switches are idle.
- 15 74. In a telephone system, a series of main selector switches, means for controlling the selecting operations of said series of main switches, auxiliary switches accessible thereto, lines accessible to said auxiliary switches, a guarding potential circuit allotted to each line, means for applying a potential to said circuits for making all of said lines busy to the auxiliary switches and means for making said auxiliary switches busy to said series 25 of main switches through the medium of said trunk controlling means for the first series of switches, while said auxiliary switches are idle.

- 20 75. In a telephone system, a series of main selector switches, means for controlling the selecting operations of said series of main switches, auxiliary switches accessible thereto, lines accessible to said auxiliary switches, means for making all of said lines busy to the auxiliary switches and means for making said auxiliary switches busy to said series 30 of main switches through the medium of said trunk controlling means for the first series of switches, while said auxiliary switches are idle.
- 35 76. In a telephone system, a series of main selector switches, means for controlling the selecting operations of said series of main switches, auxiliary switches accessible thereto, lines accessible to said auxiliary switches, means for making all of said lines busy to the auxiliary switches and means for making said auxiliary switches busy to said series 40 of main switches through the medium of said trunk controlling means for the first series of switches while said auxiliary switches are idle, said first means comprising guarding potential circuits, and said second means each comprising a guarding potential circuit.

- 50 77. In a telephone system, a series of main selector switches, means for controlling the selecting operations of said series of main switches, auxiliary switches accessible thereto, lines accessible to said auxiliary switches, means for making all of said lines busy to the auxiliary switches and means for making said auxiliary switches busy to said series 55 of main switches through the medium of said trunk controlling means for the first series of switches while said auxiliary switches are idle, said first means comprising a guarding potential circuit allotted to each line, and said second means comprising a guarding potential circuit allotted to each auxiliary switch.
- 60 78. In a telephone system, a plurality of trunks, a plurality of switches for automatically connecting with idle trunks, greater in number than said trunks, electrically controlled means for automatically selecting idle switches, and electromagnets and circuits serving automatically to prevent further seizure of idle switches after and while the trunks are all in use.

73 79. In a telephone system, a plurality of trunks, switches for automatically connecting with idle trunks, greater in number than said trunks, electrically controlled means for automatically selecting idle switches, and circuits for automatically establishing a guarding potential for all idle switches so after and while the trunks are all in use.

75 80. In a telephone system, a plurality of switchboards, trunks leading therefrom, switches individual to each board for seizing said trunks, electrically controlled means for automatically selecting idle switches on said boards, and electromagnets and circuits automatically serving when the trunks on any board are all in use to divert the automatic selection of switches to some other board.

85 81. In a telephone system, a plurality of switchboards, trunks leading therefrom, switches on each board greater in number than the trunks leading therefrom, electrically controlled means for automatically selecting idle switches on said boards, electromagnets and circuits for preventing further selection of idle switches on any board when all the trunks thereof are busy, there being trunk lines leading to said boards so disposed that any attempted selection of an idle switch on a board when all the trunks leading therefrom are busy will be diverted to another board.

90 82. In a telephone system, a plurality of non-numerical trunking switchboards with trunks leading therefrom, each switchboard comprising a plurality of non-numerical switches, automatic progressively movable means for extending connections to said board via said switches, and devices rendered operative only by the simultaneous use of all the trunks on any board to divert the calls to other boards, and rendering the non-numerical switches of the busy board inaccessible.

95 83. In a telephone system, a plurality of trunks, a plurality of switches for automatically connecting with idle trunks, greater in number than said trunks, means for automatically selecting idle switches, and means serving automatically to prevent further seizure of idle switches after and while the trunks are all in use.

100 84. In a telephone system, a plurality of trunks, switches for automatically connecting with idle trunks, greater in number than said trunks, means for automatically selecting idle switches, and means for automatically establishing a guarding potential for all idle switches so after and while the trunks are all in use.

105 85. In a telephone system, a plurality of trunks, switches for automatically connecting with idle trunks, greater in number than said trunks, means for automatically selecting idle switches, and means for automatically establishing a guarding potential for all idle switches so after and while the trunks are all in use.

- 110 86. 77. In a telephone system, a plurality of

all idle switches after and while the trunks are all in use.

84. In a telephone system, a plurality of switchboards, trunks leading therefrom, switches on each board greater in number than the trunks leading therefrom, means for automatically selecting idle switches on said boards, means for preventing further selection of idle switches on any board when all the trunks thereof are busy, there being trunk lines leading to said boards so disposed that any attempted selection of an idle switch on a board when all the trunks leading therefrom are busy will be diverted to another board.

85. In a telephone system, a plurality of non-numerical trunking switchboards, the switches on any board being greater in number than the trunks leading therefrom, means for automatically selecting idle switches on said boards, and means for preventing further selection of idle switches on any board when the other switches and all the trunks are in use, there being trunk lines leading to said boards so arranged that the prevented selection will be diverted to another board.

86. In a telephone system, a plurality of trunks, a plurality of switches for automatically connecting with idle trunks, greater in number than said trunks, means for automatically selecting idle switches, means serving automatically to prevent further seizure of idle switches after and while the trunks are all in use, telephone lines, a central source of talking and operating current, and connectors provided with means for bridging said source of current across any called telephone line.

87. In a telephone system, a plurality of trunks, switches for automatically connecting with idle trunks, greater in number than said trunks, means for automatically selecting idle switches, means for automatically establishing a guarding potential for all idle switches after and while the trunks are all in use, telephone lines, a central source of talking and operating current and connectors provided with means for bridging said source of current across any called telephone line.

88. In a telephone system, a plurality of switchboards, trunks leading therefrom, means for automatically selecting idle switches on said boards, means automatically serving when the trunks on any board are all in use to divert the automatic selection to some other board, telephone lines, a central source of talking and operating current, and connectors provided with means for bridging said source of current across any called telephone line.

89. In a telephone system, a plurality of switchboards, trunks leading therefrom, switches on each board greater in number than the trunks leading therefrom, means

for automatically selecting idle switches on said boards, means for preventing further selection of idle switches on any board when all the trunks thereof are busy, there being trunk lines leading to said boards so disposed that any attempted selection of an idle switch on a board when all the trunks leading therefrom are busy will be diverted to another board, telephone lines, a central source of talking and operating current, and connectors provided with means for bridging said source of current across any called telephone line.

90. In a telephone system, a plurality of non-numerical trunking switchboards with trunks leading therefrom, means for extending calling connections to said boards, devices rendered operative only by the simultaneous use of all of the trunks on any board to divert the calls to other boards, telephone lines, a central source of talking and operating current and connectors provided with means for bridging said source of current across any called telephone line.

91. In a telephone system, a plurality of non-numerical trunking switchboards, the switches on any board being greater in number than the trunks leading therefrom, means for automatically selecting idle switches on said boards, means for preventing further selection of idle switches on any board when the other switches and all the trunks are in use, there being trunk lines leading to said boards so arranged that the prevented selection will be diverted to another board, telephone lines, a central source of talking and operating current, and connectors provided with means for bridging said source of current across any called telephone line.

92. In a telephone system, a plurality of trunks, a plurality of switches for automatically connecting with idle trunks, greater in number than said trunks, means for automatically selecting idle switches, means serving automatically to prevent further seizure of idle switches after and while the trunks are all in use, a numerical switch for each trunk, and lines leading from each numerical switch, which lines are divided into groups, each numerical switch having motion in one plane to select a group and then in another plane at an angle to the first plane to find a line in the selected group.

93. In a telephone system, a plurality of trunks, switches for automatically connecting with idle trunks, greater in number than said trunks, means for automatically selecting idle switches, means for automatically establishing a guarding potential for all idle switches after and while the trunks are all in use, a numerical switch for each trunk, and lines leading from each numerical switch, which lines are divided into groups, each numerical switch having motion in one plane to select a group and then in another

plane at an angle to the first plane to find a line in the selected group.

94. In a telephone system, a plurality of switchboards, trunks leading therefrom, switches individual to each board for seizing said trunks, means for automatically selecting idle switches on said boards, means automatically serving when the trunks on any board are all in use to divert the automatic selection to some other board, a numerical switch 10 for each trunk, and lines leading from each numerical switch, which lines are divided into groups, each numerical switch having motion in one plane to select a group and then in another plane at an angle to the first plane to find a line in the selected group.

95. In a telephone system, a plurality of switchboards, trunks leading therefrom, switches on each board greater in number than the trunks leading therefrom, means 20 for automatically selecting idle switches on said boards, means for preventing further selection of idle switches on any board when all the trunks thereof are busy, there being trunk lines leading to said boards so disposed that any attempted selection of an idle switch on a board when all the trunks leading therefrom are busy will be diverted to another board, a numerical switch for each trunk, and lines leading from each numerical switch, which lines are divided into groups, each numerical switch having motion in one plane to select a group and then in another plane at an angle to the first plane to find a line in the selected group.

96. In a telephone system, a plurality of non-numerical trunking switchboards with trunks leading therefrom, means for extending calling connections to said boards, devices rendered operative only by the simultaneous use of all the trunks on any board to divert the calls to other boards, a numerical switch for each trunk, and lines leading from each numerical switch, which lines are divided into groups, each numerical switch 40 having motion in one plane to select a group and then in another plane at an angle to the first plane to find a line in the selected group.

97. In a telephone system, a plurality of non-numerical trunking switchboards, the switches on any board being greater in number than the trunks leading therefrom, means for automatically selecting idle switches on said boards, means for preventing further selection of idle switches on any 50 board when the other switches and all the trunks are in use, there being trunk lines leading to said boards so arranged that the prevented selection will be diverted to another board, a numerical switch for each trunk, and lines leading from each numerical switch, which lines are divided into groups, each numerical switch having motion in one plane to select a group and then in another plane at an angle to the first 60 plane to find a line in the selected group.

98. In a telephone system, a plurality of switchboards, trunks leading therefrom, switches individual to each board for seizing said trunks, means for automatically selecting idle switches on said boards, and means automatically serving when the trunks on any board are all in use to divert the automatic selection of switches to some other board. 70

99. In a telephone system, a plurality of non-numerical trunking switchboards with trunks leading therefrom, each switchboard comprising a plurality of non-numerical switches, means for extending calling connections to said boards via said switches, and devices rendered operative only by the simultaneous use of all the trunks on any board to divert the calls to other boards and render the non-numerical switches of the busy board inaccessible. 80

100. In a telephone system, primary line switches divided into groups, a master switch for controlling each group of line switches, secondary line switches divided into groups, trunk lines leading from said primary to 90 said secondary line switches, secondary trunk lines leading out of said groups of secondary line switches, and means for operating said master switches when all the secondary trunk lines leading out of a particular group are in use. 95

101. In a telephone system, a plurality of groups of primary line switches, a master switch for controlling each group, a plurality of groups of secondary line switches, a secondary master switch for controlling each group of secondary line switches, trunk lines leading from said primary to said secondary line switches, secondary trunk lines leading out of said secondary line switches, and means for operating said primary master switches when all the secondary trunks leading out of a particular group of secondary line switches are in use. 100

102. In a telephone system, a plurality of groups of primary line switches, a master switch for controlling each group, a plurality of groups of secondary line switches, trunk lines leading out from each board of primary line switches and distributed among 110 a plurality of boards of secondary line switches, secondary trunk lines leading out of said secondary line switches, and means for operating said primary master switches when all of the secondary trunks leading 115 out of a particular group are in use. 120

103. In a telephone system, a plurality of groups of primary line switches, a master switch for controlling each group, a plurality of groups of secondary line switches, a secondary master switch for controlling each group of secondary line switches, trunk lines leading out from each group of primary line switches and distributed among 125 a plurality of groups of secondary line switches 130

switches, secondary trunk lines leading out of each group of secondary line switches, and means for operating said primary master switches when all of the secondary trunks leading out of a particular group of secondary line switches are in use.

104. In a telephone system, a plurality of groups of primary line switches, each of said line switches including a plunger, a master switch for each group of primary line switches having a shaft with which said plungers are normally in engagement and adapted to be disengaged therefrom upon the operation of said line switches, a group of secondary line switches divided into groups, trunk lines leading from said primary to said secondary line switches, secondary trunk lines leading out of said groups of secondary line switches, and means for operating said primary master switches to connect all the plungers of the line switches with the corresponding shaft when all the secondary trunks leading out of a group are in use.

105. In a telephone system, primary line switches divided into groups, a master switch for controlling each group of line switches, secondary line switches divided into groups, trunk lines leading from said primary to said secondary line switches, secondary trunk lines leading out of said groups of secondary line switches, means for operating said master switches when all the secondary trunk lines leading out of a particular group are in use, said means comprising bank contacts on said primary master switches corresponding to the trunks leading to said secondary switches, and means for placing a guarding potential on said bank contacts of trunk lines extending to a group of secondary line switches when all of the trunks leading out of said group are in use.

106. In a telephone system, a plurality of groups of primary line switches, a master switch for controlling each group, a plurality of groups of secondary line switches, a secondary master switch for controlling each group of secondary line switches, trunk lines leading from said primary to said secondary line switches, secondary trunk lines leading out of said secondary line switches, means for operating said primary master switches when all the secondary trunks leading out of a particular group of secondary line switches are in use, said means comprising bank contacts on said primary master switches corresponding to the trunks leading to said secondary switches, and means for placing a guarding potential on said bank contacts of trunk lines extending to a group of secondary line switches when all of the trunks leading out of said group are in use.

107. In a telephone system, a plurality of groups of primary line switches, a master

switch for controlling each group, a plurality of groups of secondary line switches, trunk lines leading out from each group of primary line switches and distributed among a plurality of groups of secondary line switches, secondary trunk lines leading out of said secondary line switches, means for operating said primary master switches when all of the secondary trunks leading out of a particular group are in use, said means comprising bank contacts on said primary master switches corresponding to the trunks leading to said secondary switches, and means for placing a guarding potential on said bank contacts of trunk lines extending to a group of secondary line switches when all of the trunks leading out of said group are in use.

108. In a telephone system, a plurality of groups of primary line switches, a master switch for controlling each group, a plurality of groups of secondary line switches, a secondary master switch for controlling each group of secondary line switches, trunk line leading out from each group of primary line switches and distributed among a plurality of groups of secondary line switches, secondary trunk lines leading out of each group of secondary line switches, means for operating said primary master switches when all of the secondary trunks leading out of a particular group of secondary line switches are in use, said means comprising bank contacts on said primary master switches corresponding to the trunks leading to said secondary switches, and means for placing a guarding potential on said bank contacts of trunk lines extending to a group of secondary line switches when all of the trunks leading out of said group are in use.

109. In a telephone system, a plurality of groups of primary line switches, each of said line switches including a plunger, a master switch for each group of primary line switches having a shaft with which said plungers are normally in engagement and adapted to be disengaged therefrom upon the operation of said line switches, a group of secondary line switches divided into groups, trunk lines leading from said primary to said secondary line switches, secondary trunk lines leading out of said groups of secondary line switches, means for operating said primary master switches to connect all the plungers of the line switches with the corresponding shaft when all the secondary trunks leading out of a group are in use, said means comprising bank contacts on said primary master switches corresponding to the trunks leading to said secondary switches, and means for placing a guarding potential on said bank contacts of trunk lines extending to a group of secondary line switches when all of the trunks leading out of said group are in use.

when all of the trunks leading out of said group are in use.

110. In a telephone system, primary and secondary line switches divided into groups, 5 trunk lines leading from said primary to said secondary groups and trunk lines leading out of said secondary groups, the trunks leading into a group being greater in number than those leading out of a group, and the auxiliary switch and means for making said auxiliary switch busy to said main switch, said second means comprising a 70 guarding potential circuit allotted to said auxiliary switch, said second means controlled by said automatic progressively movable switch.

10 then those leading out of a group, and
means for preventing any trunk line leading
into a group being seized when all the trunks
leading out of that group are in use.

111. In a telephone system, switches divided into groups, trunks leading to said groups and trunks less in number leading out of said groups, and means for preventing any trunk leading into a group being seized when all the trunks leading out of that group are in use.

20 112. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said second means controlled by said automatic progressively movable switch.

30 113. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said first means comprising a guarding potential circuit, said second means controlled by said automatic progressively movable switch.

114. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said first means comprising a guarding potential circuit allotted to said line, said second means controlled by said automatic progressively movable switch.

115. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said second means comprising a guarding potential circuit, said second means controlled by said automatic progressively movable switch.

116. In a telephone system, a main switch, a non-numerical auxiliary switch accessible thereto, a line accessible to said auxiliary

switch, an automatic progressively movable switch, means for making said line busy to the auxiliary switch and means for making said auxiliary switch busy to said main switch, said second means comprising a guarding potential circuit allotted to said auxiliary switch, said second means controlled by said automatic progressively movable switch. 70

117. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said first and second means comprising a guarding potential circuit, said second means controlled by said automatic progressively movable switch. 85

118. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said first means comprising a guarding potential circuit allotted to said line, and said second means comprising a guarding potential circuit allotted to said auxiliary switch, said second means controlled by said automatic progressively movable switch. 95

119. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said second means comprising the auxiliary switch, said second means controlled by said automatic progressively movable switch. 100 105

120. In a telephone system, a trunking switch, means for controlling the trunking operations of said switch, a non-numerical auxiliary switch accessible thereto, a line accessible to said auxiliary switch, an automatic progressively movable switch, means for making said line busy to the auxiliary switch and means for making said auxiliary switch busy to said trunking switch through the medium of said trunk controlling means for the first switch, said second means controlled by said automatic progressively movable switch.

121. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said second means comprising the 125 130

ing said auxiliary switch busy to said main switch, said first and second means each comprising a guarding potential circuit, said second means controlled by said automatic progressively movable switch, said movable switch controlled by the guarding potential of said second means.

131. In a telephone system, a main switch, a non-numerical auxiliary switch accessible thereto, a line accessible to said auxiliary switch, an automatic progressively movable switch, means for making said line busy to the auxiliary switch and means for making said auxiliary switch busy to said main switch, said first means comprising a guarding potential circuit allotted to said line, said second means comprising a guarding potential circuit allotted to said auxiliary switch, said second means controlled by said automatic progressively movable switch, said movable switch controlled by the guarding potential of said second means.

132. In a telephone system, a main selector switch, means for controlling the selecting operations of said switch, a non-numerical auxiliary switch accessible thereto, a line accessible to said auxiliary switch, an automatic progressively movable switch, means for making said line busy to the auxiliary switch, and means for making said auxiliary switch busy to said main switch, through the medium of said controlling means for the first switch, said second means comprising a guarding potential circuit, said second means controlled by said automatic progressively movable switch, said movable switch controlled by the guarding potential of said second means.

133. In a telephone system, a main selector switch, means for controlling the selecting operations of said switch, a non-numerical auxiliary switch accessible thereto, a line accessible to said auxiliary switch, an automatic progressively movable switch, means for making said line busy to the auxiliary switch, and means for making said auxiliary switch busy to said main switch, through the medium of said controlling means for the first switch, said second means comprising a guarding potential circuit allotted to said auxiliary switch, said second means controlled by said automatic progressively movable switch, said movable switch controlled by the guarding potential of said second means.

134. In a telephone system, a main selector switch, means for controlling the selecting operations of said switch, a non-numerical auxiliary switch accessible thereto, a line accessible to said auxiliary switch, an automatic progressively movable switch, means for making said line busy to the auxiliary switch and means for making said auxiliary switch busy to said main switch, through

the medium of said controlling means for the first switch, said first and second means each comprising a guarding potential circuit, said second means controlled by said automatic progressively movable switch, said movable switch controlled by the guarding potential of said second means.

135. In a telephone system, a main selector switch, means for controlling the selecting operations of said switch, a non-numerical auxiliary switch accessible thereto, a line accessible to said auxiliary switch, an automatic progressively movable switch, means for making said line busy to the auxiliary switch and means for making said auxiliary switch busy to said main switch through the medium of said controlling means for the first switch, said first means comprising a guarding potential circuit allotted to said line, and said second means comprising a guarding potential circuit allotted to said auxiliary switch, said second means controlled by said automatic progressively movable switch, said movable switch controlled by the guarding potential of said second means.

136. A telephone system comprising a subscriber's line, first selectors assigned for connection from said line as a calling line and each having a definite number of passive contacts, second selectors exceeding in number said definite number of passive contacts of each first selector, and means for connecting said line as a calling line through a first selector to any of said second selectors.

137. A telephone system comprising a group of subscribers' lines, a group of first selectors assigned for connection from said subscribers' lines as calling lines and each having a definite number of passive contacts, second selectors of a number exceeding said definite number of passive contacts in each first selector, and means for connecting any said subscriber's line as a calling line through a first selector to any one of said second selectors.

138. A telephone system comprising a subscriber's line, first selectors common to said line when calling, said first selectors having passive bank contact sets, second selectors exceeding in number the number of passive contact sets of any of said first selectors, and means for connecting said line as a calling line through a first selector to any of said second selectors.

139. A telephone system comprising a group of subscribers' lines, first selectors common to said lines when calling, said first selectors having passive bank contact sets, second selectors exceeding in number the number of passive contact sets of any of said first selectors, and means for connecting any one of said lines when calling through a first selector to any of said second selectors.

140. A telephone system comprising subscribers' lines, first selectors common to said lines when calling, said first selectors having passive bank contact sets, second selectors exceeding in number the number of passive contact sets of any of said first selectors, and automatic switches less in number than the number of lines and connections therefrom for connecting any one of said lines when calling through a first selector to any of said second selectors.

141. In a telephone system, a plurality of forward selecting non-numerical trunking switches, a plurality of numerical switches, and a temporarily established talking circuit between a calling and a called line including all of said switches in series.

142. In a telephone system, a train of automatic directively movable switches operable in accordance with all the digits of a called number for extending a connection to a called line, a secondary non-directive trunking switch for extending connection to the first switch in said train, and a primary non-directive trunking switch for extending the calling line to said secondary switch.

143. In a telephone system, two serially related trunk lines each having talking conductors for inclusion in a talking connection between a calling and a called line, a non-directive primary trunking switch for extending the calling line to the first of said trunk lines, a non-directive secondary trunking switch for connecting the first and second trunk lines, and subscriber controlled directive switches for completing the connection from the second trunk line to the called line.

144. In a telephone system, two serially related trunk lines for use in a connection between a calling and a called line, a non-directive primary trunking switch individual to the calling line for extending the same to said first trunk line, a non-directive secondary trunking switch individual to said first trunk line for connecting the two trunk lines, subscriber controlled directive switches operable in accordance with the called number to complete the connection from the second trunk line to the called line, and means for supplying talking current to

the calling line over the conductors of said trunk lines in series.

145. In a telephone system, subscribers' lines divided into groups, groups of non-numerical individual primary line switches corresponding to said groups of lines, groups of non-numerical secondary line switches, a trunk line connecting each primary group with each secondary group, selector switches accessible to the secondary switches, and circuit arrangements rendered effective by the subscriber on a calling line for operating the associated individual switch and one of said secondary switches to connect the calling line with an idle selector.

146. In a telephone system, subscribers' lines divided into groups, groups of non-numerical individual primary line switches corresponding to said groups of lines, groups of non-numerical secondary line switches, a trunk line connecting each primary group with each secondary group, selector switches accessible to the secondary switches, a control circuit including a calling line for operating the associated individual switch to connect with a secondary switch over one of said trunk lines, and a local control circuit excluding the calling line and completed by the operated primary switch for operating the connected secondary switch to extend the calling line to an idle selector switch.

147. In a telephone system, groups of final connectors, subscribers' lines divided into groups in accordance with the capacity of the said connectors, groups of individual non-numerical primary line switches corresponding to said groups of lines, groups of selector switches, groups of non-numerical secondary line switches inserted in the system between the primary switches and said selector switches, and trunk lines connecting said primary and secondary groups and so disposed that the said selectors are made accessible in common to all said primary switches.

Signed by me at Chicago, Cook County, Illinois, this 17th day of May, 1907.

ALEXANDER E. KEITH.
